TELEPHONE SYSTEM

Harry Paul Mahoney and Clarence Ernest Lomax,
Oak Park, Ill., assignors to Associated Electric
Laboratories, Inc., Chicago, Ill., a corporation of
Delaware

Application March 16, 1938, Serial No. 196,136

62 Claims. (Cl. 179—17)

The present invention relates to improvements in telephone systems and has for one of its objects the provision of improved apparatus for terminating multiparty rural subscribers' lines in a telephone exchange which utilizes automatic switching equipment for setting up connections between the various lines of the system.

In the usual arrangement of existing installed automatic exchanges, wherein certain of the lines extending to the exchange are of the rural multiparty type and others are of the single party type, no differentiation is made between the lines as regards the mode of terminating the lines in the automatic switching equipment. As a result, the initiation of a reverting call on one of the rural lines usually results in the seizure of certain of the regular automatic switching equipment provided in the terminating exchange. More particularly, when a reverting call is initiated on a rural line, one of the non-numerical automatic switches provided in the exchange is assigned to the use of the line having the calling condition created thereon and operates to switch the calling line through to one of the numerical impulse responsive switches. In certain instances, the seized switches are held operated for the duration of the reverting call. In other systems, apparatus is provided for causing the release of the operated switches after a predetermined time interval has elapsed following the seizure of the switches. In either case, certain of the regular automatic switching equipment is tied up so that it can not be used by the other lines.

It is a further object of the present invention, therefore, to provide in an automatic telephone system apparatus for preventing any of the regular switching equipment provided in an automatic exchange from being taken for use by a line having access to the equipment when a reverting call is initiated on the line.

More specifically, it is an object of the invention to provide in an automatic telephone system an improved arrangement wherein the regular automatic switching equipment is only rendered accessible to a multiparty rural subscriber's line when a preliminary digit is dialed at a calling substation associated with the line.

It is a further object of the invention to provide an arrangement for testing the impulse transmitting efficiency of the line during the dialing of the preliminary digit and to prevent any of the regular automatic switching equipment from responding to further impulses dialed at the calling substation in the event the impulse transmitting

efficiency of the line is found to be extremely poor.

It is an additional object of the invention to provide, in conjunction with the regular automatic switching equipment of an automatic exchange, improved apparatus for controlling the selective signalling of the substations associated with a multiparty line terminating at the switching equipment having access to the line.

It is another object of the invention to provide an improved arrangement for guarding the multiparty lines against seizure by the automatic switching equipment having access thereto during intervals when the rural lines are occupied with reverting calls.

In the illustrated embodiment of the invention, the multiparty rural subscribers' lines extending to the exchange are terminated at a group of improved numerical or connector switches by way of which connections are routed from the single party lines of the system to the rural lines. The rural lines are also terminated in the bank contacts of a group of auxiliary automatic switches which function to render the regular automatic switching equipment provided in the exchange accessible thereto. More particularly, there is provided in association with the group of rural lines a plurality of test or finder-repeater links, the respective repeater portions of which are connected by way of trunk lines to certain of the non-numerical switches located in the exchange. Allotter means are provided in association with the several finder-repeater links for the purpose of assigning these links to successive calling ones of the rural subscribers' lines in a definite order. Individually provided at the respective substations associated with the respective rural lines are manually operable magneto generators which are used for signalling between the substations of the lines on reverting calls. The arrangement is such that an idle one of the finder-repeater links is assigned to the use of any line when a call is initiated on the line through the operation of one of the generators provided at one of the substations associated therewith. The seizure of a finder-repeater link does not, however, result in the seizure of any of the regular automatic switching equipment, each link being so arranged that it functions to switch the connection through to one of the numerical switches only in response to the transmission of a predetermined series of impulses thereto by way of the calling subscriber's line or, in other words, in response to a predetermined operation of the impulsive device provided at the calling substation.

associated with the calling line. More specifically, there is provided in each link an impulse responsive relay which is adapted to be connected to respond to impulses transmitted by way of a seized calling line and in cooperation with the associated control apparatus functions to condition certain of the automatic switching equipment to respond to further operation of the impulsive relay. This control apparatus is so arranged that an artificial leak impedance is connected across the calling line during the dialing of the preliminary digit, whereby the sensitivity of the impulsive relay is reduced during the transmission of the first impulse series and this relay is tested to determine its responsiveness to the transmitted impulses. In the event it is found that the impulsive relay is not faithfully responsive to the impulses of the first series, the control apparatus functions to prevent any of the automatic switching equipment from responding to further operation of the impulsive relay. If, however, the impulsive relay is faithfully responsive to the impulses of the first series, the control apparatus operates to disconnect the artificial leak impedance from the calling line to enhance the responsiveness of the impulsive relay to further impulses transmitted over the calling line.

A timing device is provided in common association with the several finder-repeater links and, if a call initiated on a rural line happens to be of a reverting nature, this device functions to cause the seized one of the finder-repeater links to be released a predetermined time interval after it is seized. Each link is provided with control apparatus for marking any associated calling line as busy, thereby to prevent its seizure by one of the numerical or special connector switches. When any link is released through the operation of the timing device, the above-mentioned control apparatus functions to remove the busy marking and to substitute therefor a marking identifying the associated line as idle. This apparatus further functions to signal over the calling line that the line is no longer guarded against seizure by one of the connector switches.

In accordance with a further feature of the invention, each of the improved connector or final selector switches at which the rural lines terminate is provided with two operating positions for each of the lines. There is provided in common association with this group of connector switches ringing apparatus which comprises a plurality of ringing current conductors and a cyclically operating interrupter switch of improved arrangement for impressing on the ringing current conductors the voltage of the ringing current source for coded intervals which are different for each of the conductors. The arrangement is such that, when any one of the connector switches is operated to one of the two positions corresponding to a particular line, one particular ringing current conductor is connected to project ringing current over the line and, when the switch is operated to the other of the two positions corresponding to the line, a second ringing current conductor is connected to project ringing current over the line. Further in accordance with this feature of the invention, the control apparatus provided in each of the connector switches is arranged automatically to discontinue the application of ringing current to a selected line after the current has been applied to the line for a predetermined number of ringing cycles. More specifically, the cyclically operating interrupter

switch is arranged to apply to a control conductor extending therefrom a predetermined potential at the beginning of each cycle of its operation, and a plurality of relays are provided in each connector switch which are so connected and arranged as sequentially to operate in response to successive applications of the said predetermined potential to the control conductor. The first of these relays to operate functions to connect the particular selected ringing current conductor to the selected line, and the last of the relays to operate functions to disconnect the ringing current conductor from the selected line and to connect the trunk line incoming to the connector switch to the subscriber's line.

Further features of the invention pertain to the particular arrangement of the circuit elements whereby the above and additional operating features are obtained.

The novel features believed to be characteristic of the invention are set forth with particularity in the appended claims. The invention, both as to its organization and method of operation, together with further objects and advantages thereof, will best be understood by reference to the specification taken in connection with the accompanying drawings in which Figures 1 to 5, inclusive, illustrate an automatic telephone system having incorporated therein the features of the present invention as briefly outlined above.

Referring now to the drawings, the system there illustrated comprises, in general, an exchange, a plurality of single party subscribers' lines, two of which are illustrated at 101 and 104, extending to the exchange, and a plurality of subscriber-controlled automatic switches including a line switch 100, two selector switches 120 and 140, and a connector switch 150 for setting up connections between the various subscribers' lines. Also extending to the exchange are a group of rural subscribers' lines, one of which is illustrated at 600, each of which is of the multiparty type. The rural lines are terminated in the bank contacts of a group of special connector switches, one of which is illustrated in Fig. 2, and also in 45 the finder portions of a group of finder-repeater links, one of which is shown in Fig. 4. Each repeater is connected by way of a trunk line to a line switch and is operative to render the regular automatic switching equipment accessible to the 50 rural lines. Thus, the repeater illustrated in Fig. 4 is connected by a trunk line 125 to a line switch 130 which has access to certain of the selector switches in the exchange. For the purpose of assigning the finder-repeater links to 55 successive calling ones of the rural subscribers' lines in a definite order, there is provided in association with these links an allotter switch forming a part of the common equipment indicated generally at 500. The special connector switches 60 of the group having access to the rural lines have associated therewith ringing apparatus as illustrated in Fig. 3, which functions in a manner such that selective code ringing of any desired substation on a selected rural line may be achieved.

It is pointed out that the line switches 100 and 130 and the other similar switches corresponding thereto are non-numerical switches in the sense that they are ineffective to perform any line selecting functions other than that of automatically selecting idle ones of the selector switches. The selector and connector switches, on the other hand, are commonly known as numerical switches in that they are individually operative to per-

form particular line selecting functions in response to impulses transmitted thereto. It will be understood that a plurality of switches of each type, namely, a plurality of line switches, a plurality of selector switches, and a plurality of connector switches, are provided in the system for performing the usual line switching functions. The numerical switches of each type are respectively arranged in groups and, in accordance with 5 universally followed practice, the number of switches in each group is determined by the maximum volume of traffic the particular switch group is required to handle. Further in accordance with conventional practice, each of 10 the single party subscribers' lines is multiplied to the corresponding bank contacts of a group of connector switches, whereby a plurality of switches are available for setting up connections between each line and any other line of the system. The line switches, on the other hand, are 15 individually associated with the respective subscribers' lines, that terminating the line 101 being indicated at 100.

The end of each subscriber's line remote from 20 the exchange terminates in one or more subscribers' substations, the arrangements of which are different depending upon whether the line is of the single party type or is one of the group of multiparty rural lines. Two substations of the 25 usual automatic type are diagrammatically illustrated at A and B in association with the lines 101 and 104, respectively. In brief, each of the single party line substations may comprise the usual hand set type of transmitter and receiver, 30 a cradle or hook switch, a ringer, and an impulsing device for transmitting the switch control impulses by way of the associated line to the automatic switching equipment located in the terminating exchange. These substations are of 35 the well-known common battery type. The substations associated with the respective rural lines, on the other hand, are of the local battery type, one such substation being illustrated in detail at E in Fig. 5 and two other substations of similar 40 type being diagrammatically illustrated at C and D, respectively.

Each of the line switches 100, 130, etc., is preferably of the well-known rotary type, of which there are several commercial embodiments. Each 45 of the selector and connector switches is preferably of the well-known Strowger type having embodied therein a Strowger switching mechanism including a plurality of bank contacts arranged in levels; a wiper carriage structure 50 adapted to be translated vertically to bring the wipers thereof to a position opposite a particular level of bank contacts and then rotated to bring the wipers into engagement with a particular set of contacts in a selected level; vertical, 55 rotary and release magnets; and control relays 60 suitably connected and arranged to control the energization of the various magnets and the line switching in accordance with the particular functions of the particular switch. In all fundamental 65 respects, these switches are similar to the connector switch illustrated in detail in Fig. 2. Obviously, the particular arrangement of the control apparatus embodied in the switches of different type is different in each instance, depending 70 upon the character of the switch.

Neglecting for the present the details of the apparatus terminating the multiparty rural subscribers' line, the system as described above is, in general, entirely conventional in form and its 75 operation is well understood in the art. In brief,

when a subscriber, such, for example, as the subscriber at the telephone A, initiates a call over the line 101 to a second subscriber's telephone, such, for example, as the telephone at the station B, by lifting his receiver from its hook, a loop circuit is completed by way of the line 101 for initiating the operation of the line switch 100 to select a trunk line leading to an idle selector switch. Assuming, for example, that the selector switch 120 is the first numerical switch selected 10 for the use of the calling line 101, when the trunk line leading to this selector switch is found, the loop circuit is extended to this switch and the switch is conditioned to respond to the first series of impulses dialed at the calling substation. With 15 the selector switch 120 in this condition, dial tone is returned over the established loop to the calling subscriber to indicate that the dialing operation may be started. When the first digit is dialed at the calling substation, the switch 20 120 elevates its wipers to a position opposite the level of bank contacts terminating the trunk lines respectively extending to the connector switches having access to the called line 104. Following this operation, the wipers of the switch 25 120 are automatically stepped over the contacts of the selected level until a trunk line leading to an idle connector switch of the selected group is found. Assuming that the connector switch 150 is the first idle connector switch available, 30 when the wipers of the switch 120 are stepped into engagement with the contacts terminating the trunk line extending to this connector switch, the subscriber's loop circuit is extended thereto, thereby to cause this connector switch to be conditioned to respond to the second and third series of impulses dialed at the calling substation. In 35 response to the dialing of the second digit, the wipers of the connector switch 150 are stepped vertically to a position opposite the level of bank contacts at which are terminated the lines of the ten-line subgroup including the called line 104. Following this series of impulses, the connector switch is conditioned to rotate its wipers step-by-step in accordance with the impulses making 40 up the third and final digit dialed at the calling substation. When the last digit is dialed, the wipers of the switch 150 are stepped into engagement with the set of bank contacts terminating the called line 104. In accordance with conventional 45 practice, suitable provisions are made in the connector switch 150 for testing the called line to determine its idle or busy condition, for returning busy tone over the established loop to the calling subscriber in case the called line is busy and for applying ringing current to the called line in the event this line is idle at the time it is selected. Assuming that the line 104 is idle, the desired conversational connection is completed when the called substation B is answered. Also in accordance with conventional 50 practice, the apparatus is arranged to insure its release when the connection is cleared out at the calling and called substations. Any desired mode of initiating the release of the established switch train may be utilized. For example, the control apparatus embodied in the connector switch 150 55 may be so arranged that the release of the connection is entirely under the control of the calling party. Alternatively, the apparatus may be so arranged that the release of the connection is under the control of the last party to hang up.

As indicated above, each of the substations associated with the rural subscribers' lines is of the local battery type. More particularly, the substation E illustrated in Fig. 5 comprises a trans- 75

mitter 614 which is arranged to be connected in a closed circuit including the primary winding 611 of a transformer 610 and a local battery 613 through the operation of a hook switch 620. The 5 substation equipment further comprises a receiver 615, an impulsing device 630, an alternating current generator 605 of the magneto type, and a signal device in the form of a ringer 603 which is normally connected across the conductors of the 10 line 600 over a path including a condenser 604 and certain of the springs embodied in the hook switch 620. It will be understood that the magneto or alternating current generators individually provided at the substations associated with 15 the line 600 comprise means for signalling between the substations on this line on reverting calls.

Referring now more particularly to the finder-repeater links by way of which connections are 20 routed from the rural subscribers' lines to the regular automatic switching equipment and considering the link illustrated in Fig. 4 as exemplary, this link comprises a finder switch 490 of the well-known rotary type. In brief, the finder switch 25 comprises four sets of bank contacts 491 to 494, inclusive, wipers 495 to 498, inclusive, individually associated with the respective bank contact sets, a motor magnet 499 for driving the wipers over the contacts of their respective associated sets, 30 and a switching-through relay R410 for connecting any selected calling line through to the repeater portion of the link.

For the purpose of assigning idle ones of the 35 finder-repeater links to the various successive calling ones of the rural lines in a definite order and for the further purpose of controlling the operation of a selected finder switch to search for and seize a calling line, there is provided in association with the finder-repeater links the 40 common equipment 500. This common equipment includes a rotary link allotter switch having five sets of bank contacts 501 to 505, inclusive, wipers 506 to 510, inclusive, respectively associated with the bank contact sets, a motor magnet 45 511 for driving the enumerated wipers over the contacts of their associated sets, a start relay R520, and three relays R530, R540 and R550 for controlling the operation of the rotary switch to 50 find an idle link and for controlling the operation of the finder portion of a selected link to find a calling line.

In order to initiate the operation of the common equipment 500 when a calling condition is 55 created on one of the rural subscribers' lines, each line has individually associated therewith an alternating current relay which is operative in response to the operation of any one of the magneto generators provided at the substations on the associated line. Such a relay is indicated at 60 R405 as including a winding normally connected across the line conductors of the line 600. In order to prevent the operation of this relay when the associated line is seized by one of the special connector switches, a cut-off relay R400 is provided which operates to disconnect the upper or 65 alternating current winding of R405 from across the conductors of the line 600 in response to the seizure of the line 600 by any one of the connector switches.

The repeater portion of the link illustrated in Fig. 4 comprises a repeating coil 472, a line or impulse responsive relay R415, a slow-to-release hold relay R430, an impulse correcting network 70 comprising the three relays R420, R440 and R450,

and a switching-through relay R460 which is under the control of an impulse responsive switch 480. The relay R450 is a pulsing relay which responds to the operation of R415 and functions to repeat impulses to the switch 480 and to the 10 automatic switches constituting the regular automatic switching equipment. The switch 480 is of the well-known minor type and comprises two sets of bank contacts 481 and 482, wipers 483 and 484 respectively associated with the contact sets 15 481 and 482, an operating magnet 485 for driving the wipers 483 and 484 over the contacts of their respective associated sets, a release magnet 487, and off-normal springs 486 for controlling the energization of the release magnet. There are also provided in the repeater portion of the link two relays R470 and R475 which function to 20 control the operation of the switch 480.

For the purpose of releasing the link a pre-determined time interval after it has been assigned to the use of a line having a reverting call initiated thereon, there are provided three additional relays R560, R570 and R580, the last two of which are under the control of a pulse generator 575. The relay R560 also functions as a device for marking the link illustrated as busy in the bank contacts of the allotter switch and as a hold relay for maintaining the link operated following the extension of a subscriber's loop circuit to the repeater portion thereof. The pulse generator 575 may be of any well-known construction which includes means for alternately applying ground pulses to the time pulse leads C567 and C573 at spaced intervals. If desired, 35 it may comprise a commutator driven by a synchronous motor through a speed reducing mechanism and including grounded commutator segments suitably arranged to engage brushes respectively terminating the leads C567 and C573. 40

Referring now more particularly to the group of improved connector switches by way of which the regular automatic subscribers' lines gain access to the rural lines, it is pointed out that the connector switches of this group may be of identical construction and arrangement. For this reason, only the switch illustrated in Fig. 2 will be described in detail, but it will be understood that each of the rural lines is multiplied to the corresponding bank contacts of each of the 50 switches of this group. In brief, the switch shown in Fig. 2 comprises a switching mechanism 244, of the Strowger type, which includes a plurality of bank contacts arranged in levels; wipers for engaging the contacts; means comprising a vertical magnet 297 and a ratchet and pawl mechanism, not shown, for translating the wipers to a position opposite a desired contact level; means comprising a rotary magnet 295 and a ratchet and pawl mechanism, not shown, for thereafter 55 rotating the wipers step by step into engagement with a selected contact set in the selected level; a release magnet 239 for causing the wiper carriage structure to be returned to normal during the release of the switch, vertical off-normal springs 265 and a plurality of control relays for controlling the operation of the three enumerated magnets and the auxiliary functions of the switch. Of these relays, R200 is the usual line 60 or impulsing relay, R204 is the usual hold relay and is of the slow-to-release type, R210 and R220 are slow-to-release pulse circuit control relays, R230 is a ringing control relay, and R214 is the 65 busy test relay. The remaining relays illustrated 70

75

in Fig. 2, namely, R240, R250, R260 and R270, are provided in accordance with one feature of the present invention for controlling the ring cut-off operation and the line switching operation in an improved manner. For the purpose of selectively signalling the various substations associated with the rural subscribers' lines, coded ringing is utilized. To this end, the code selecting switch 280 is provided in the connector switch and is arranged to respond to impulses transmitted thereto by way of a calling line. This code selector switch is of the well-known minor type and comprises two sets of bank contacts 281 and 282 at which are terminated two groups of ringing current conductors, each comprising ten conductors, wipers 283 and 284 respectively associated with the contact sets 281 and 282, an operating magnet 228 for driving the enumerated wipers over the contacts of their respective associated sets, a release magnet 229 operative to restore the switch to normal, and off-normal springs 285 for controlling the energization of the release magnet. For the purpose of separating the local battery talking circuits, normally formed when the rural lines are involved in connections, from the common battery talking circuits used in connections between the regular automatic subscribers' lines, there is provided a repeater 290 which is inserted in and divides into two sections the trunk line incoming to the connector switch illustrated in Fig. 2.

The ringing current conductors terminated at the bank contacts of the code selector switch 280 form a cable 314 extending to the bank contacts of an interrupter switch 300, illustrated in Fig. 3. The switch 300 is of the well-known rotary type and comprises a plurality of sets of bank contacts 382 to 392, inclusive, wipers 370 to 380, inclusive, respectively associated with the bank contact sets, and means comprising an operating magnet 365 and a ratchet and pawl mechanism, not shown, for driving the enumerated wipers over the contacts of their respective associated contact sets. This switch functions to impress on the respective ringing current conductors the voltage of an alternating current source 325 for predetermined intervals during each cycle of its operation, and the bank wiring of the switch is such that the coded voltage impressed on each conductor during each ringing cycle is different in character from that impressed on each of the other ringing current conductors. More particularly, the voltage of the source 325 is impressed on each of the enumerated wipers of the interrupter switch by way of a transformer 326 having a primary winding 327 connected across the source and a secondary winding 328 having one terminal grounded and the opposite terminal arranged to be connected to the respective wipers. The contact bank of the switch 300 is wired in an improved manner, described more particularly hereinafter, such that the coding of the ringing voltage applied to the several ringing current conductors is different for each conductor. For the purpose of controlling the operation of the interrupter switch there is provided in association therewith a start relay R310 and a group of cyclically operating slow-to-operate relays R320, R330 and R340. Specifically, this group of relays functions to connect the wipers of the interrupter switch to the winding 328 and to energize the operating magnet 365 once during each cycle of their operation.

Operation of the ringing interrupter

The operation of the ringing interrupter is initiated when ground is applied to the start conductor C316 by one of the special connector switches in the group including the switch shown in Fig. 2, to complete an obvious circuit for energizing the start relay R310. The relay R310, upon operating, completes, at RA313, a path for applying a predetermined potential, namely, ground potential, to the pick-up or control conductor C315. At RA312, the relay R310 prepares a circuit, traced hereinafter, for maintaining itself energized independently of its operating circuit as traced above and until the interrupter switch has been operated through a complete cycle. The relay R310 also completes a circuit for energizing the slow-to-operate relay R320, this circuit extending from ground at RA311 by way of the winding of R320 and the resistor 314 to battery.

The relay R320 operates, after an interval, to open, at RA321, a point in the path normally short-circuiting the winding of R330, permitting the latter relay to be energized over a circuit extending from ground at RA311 by way of the winding of R330 and the resistor 329 to battery. The slow-to-operate relay R330 operates, after an interval, to open, at RA331, a point in the path normally short-circuiting the winding of R340, permitting this latter relay to be energized over a circuit extending from ground at RA311 by way of the winding of R340 and the resistor 343 to battery. The slow-to-operate relay R340, in turn, operates, after an interval, to complete, at RA342, an obvious path for short-circuiting the energized winding of R320, causing the last-mentioned relay to restore. When R320 restores, it completes, at RA321, the path for short-circuiting the winding of R330. The relay R330 now restores to complete, at RA331, the above-mentioned path for short-circuiting the winding of R340. When R340 restores, it opens, at RA342, the path short-circuiting the winding of R320, permitting this latter relay to again be energized over its operating circuit as traced above. Thus, a second cycle of operation of the three relays R320, R330 and R340 is initiated. During each operating cycle of these three relays, a circuit is completed for energizing the operating magnet 365 embodied in the interrupter switch 300. Thus, when R340 operates, it completes, at RA341, an obvious circuit for energizing the magnet 365. Assuming the wipers of the switch to be standing in the home position as shown in the drawings, when this magnet is energized, the magnet, in co-operation with its associated ratchet and pawl mechanism, not shown, operates to step the wipers 370 to 380, inclusive, one step or into engagement with their respective associated second contacts. It is manifest that, for each succeeding cycle of operation of the three relays R320, R330 and R340, the magnet 365 is energized to cause the enumerated wipers to be moved another step. As pointed out immediately hereinafter, movement of the enumerated wipers over the contacts of their respective associated sets results in the coding of the ringing voltage applied to the various ringing current conductors terminating in the bank contacts of the code selector switch 280. This is by virtue of the particular bank wiring arrangement of the interrupter switch illustrated in Fig. 3.

This wiring arrangement is such that voltage of the ringing current source is impressed on the various ringing current conductors for short intervals of equal duration but different in number

and with different spacing intervals therebetween. Thus, as the wiper 370 travels over the first twelve contacts of the set 382, it is connected to the ringing current conductor 32 while standing 5 in engagement with its associated second, third, fourth, sixth and seventh contacts. While in engagement with each of these contacts, the voltage developed across the transformer 328 is impressed on the conductor 32 for a short interval. Thus, 10 with the wiper 370 standing in engagement with its second contact and when R330 operates during the second cycle of operation of the three relays R320, R330 and R340, a path is completed for connecting the upper terminal of the secondary 15 winding 328 to the jumper connection 389', this path extending by way of RC333 and RA332. The jumper connection noted is multiplied between the wipers 370 to 373, inclusive, and between the wipers 376 to 380, inclusive. Hence, 20 the voltage developed across the secondary winding 328 is impressed on any ones of the ringing current conductors which extend to the respective second contacts associated with the enumerated wipers. Since the second 25 contact of the set 382 is connected to the ringing current conductor 32, this conductor has impressed thereon the voltage of the ringing current source when R330 operates. Similarly, the ringing current conductors 31, 4, 34, 41, 44, 1 and 43 30 have the voltage of the source impressed thereon with the wipers of the interrupter switch standing in the position noted. When R340 operates, following the operation of R330 in the second cycle of operation of the three relays noted, the 35 magnet 365 is energized to advance the wipers into engagement with their respective associated third contacts. This movement of the wipers, however, does not result in the disconnection of the ringing current conductors from the upper 40 terminal of the secondary winding 328 for the reason that each of the wipers is of the bridging type arranged to bridge two contacts during the transition interval when it is being moved from one contact to another. When R340 operates, 45 however, it causes the rapid sequential restoration of R320 and R330 in the manner pointed out above. The last-mentioned relay, upon restoring, disconnects the jumper conductor 389' from the upper terminal of the winding 328 to remove the 50 potential of the ringing current source from the ringing conductors and to substitute ground thereon. During the third cycle of operation of the three relays R320, R330, and R340, the potential of the source is again impressed on those 55 of the ringing current conductors which are connected to the respective third contacts of the sets associated with the wipers 370 to 373, inclusive, 376 to 380, inclusive, and, during the fourth cycle of operation of these relays, the potential of the 60 source is impressed on those of the conductors connected to the fourth contacts of the sets respectively associated with the enumerated wipers, and so on. It will be noticed from an inspection of the drawings that the ringing current conductor 32, for example, is not connected to the fifth 65 contact of the set 382. Hence, during the cycle of operation of the three relays R320, R330 and R340 to advance the wipers from engagement with their respective associated fifth contacts and into 70 engagement with their respective associated sixth contacts, the potential of the ringing current source is not impressed on this particular ringing current conductor. A spacing interval is, therefore, provided between the first half of the code 75 and the second half. Since the conductor noted,

namely, the conductor 32, is connected to the sixth and seventh contacts of the set 382, this second half of the code cycle comprises two additional short ringing periods. From this point on and until the wiper 370 is advanced into engagement with the fifteenth contact of the set 382, the conductor 32 is held disconnected from the ringing current source. 5

The arrangement is such that two ringing cycles are completed during movement of the 10 switch wipers over the twenty-five points of the switch. The end of the first cycle is reached when the wipers are advanced into engagement with their respective associated thirteenth contacts, and the wipers are moved to a position to 15 begin the second ringing cycle when they are driven into engagement with their respective associated fourteenth contacts. In order to render the spacing between cycles substantially equal, it is desirable rapidly to move the wipers from 20 engagement with their respective associated thirteenth contacts and into engagement with their respective associated fourteenth contacts. To this end, the thirteenth contact of the set 386 is included in a circuit for energizing the magnet 365 25 by way of the self-interrupting contacts associated with the armature 366, this circuit being completed when the wiper 374 is advanced into engagement with the thirteenth contact of the set 386 and extending from ground on this wiper by way 30 of C336, the armature 366 and the winding of the magnet 365 to battery. When energized over the above-traced circuit, the magnet 365 operates immediately to advance the wipers into engagement with their respective associated fourteenth contacts independently of the cyclically operating 35 relays R320, R330 and R340. This operation marks the beginning of the second ringing cycle. During this second cycle, the voltage of the ringing current source is impressed on the various 40 ringing current conductors for coded intervals which are identical with those produced during the first ringing cycle. Thus, during the respective intervals when the wiper 370 is standing in engagement with the fifteenth, sixteenth, seventeenth, eighteenth, nineteenth and twentieth contacts of 45 the set 382, the voltage of the source is impressed on the conductor 32 through the operation of the relay R330. During the interval when this wiper stands in engagement with the eighteenth contact of the set 382, the conductor 32 is held disconnected from the source so that a spacing interval is provided which corresponds to that produced when the wiper is moved into engagement with its fifth contact. When the wiper 370 is 50 moved from engagement with the twentieth contact of the set 382, the voltage of the source is held disconnected from the ringing current conductor 32 until this wiper is again moved into engagement with the second contact of the set 55 382 at the beginning of the third ringing cycle. 60

As indicated above, the coding of the voltage applied to each of the ringing current conductors during each ringing cycle is different in each instance. Thus, considering the ringing current conductor 13, for example, this conductor has applied thereto the voltage of the source for a short interval, followed by three narrowly spaced short intervals which are relatively widely spaced from the first interval, during each ringing cycle. 70 More particularly, when the wiper 371 is moved into engagement with the seventh contact of the set 383 and when R330 operates, the conductor 13 is connected to the ringing current source. Thereafter and during the interval when the 75

wiper 371 is standing in engagement with the eighth contact of the set 383, the conductor 13 is held disconnected from the source. When, however, the wiper 370 is moved into engagement with the ninth contact of the set 382, this conductor is connected to the source by way of the wiper 370. Thereafter, and during the intervals when the wiper 371 is standing in engagement with the tenth and eleventh contacts of the set 383, the conductor 13 is connected to the source for short intervals measured by the time required for R330 to operate and restore. By inspection of the bank contact wiring arrangement, it will be apparent that the same coding of the voltage applied to the conductor 13 occurs during the second ringing cycle or during the movement of the wipers over the contacts numbered from 15 to 25, inclusive.

It is believed that the mode of applying the voltage of the ringing current source on the remaining ringing current conductors will be apparent from the wiring arrangement illustrated in the drawings considered in light of the preceding description pertaining to the two conductors 32 and 13. It is pointed out, however, that the number identifying each of the ringing current conductors is indicative of the particular coding of the voltage impressed, respectively, thereon. More particularly, during each ringing cycle, the conductor 12 has impressed thereon the voltage of the source for one short interval, followed by a spacing interval which is succeeded by two successive and closely spaced short ringing intervals. Similarly, the conductor 34 has impressed thereon during each ringing cycle the voltage of the source for three closely spaced short ringing intervals, followed by a spacing interval succeeded by four closely spaced short ringing intervals.

As indicated above, a predetermined potential, namely, ground potential, is impressed on the control conductor C315 for a short interval at the beginning of each ringing cycle. Thus, if the ringing apparatus is started with the interrupter switch standing in the position shown in the drawings, the path for applying ground potential to the conductor noted is completed when R310 operates. This circuit extends from ground as applied to the wiper 375 by way of the first contact of the set 387 and RA313 to C315. Again, when the wipers are driven over their associated contacts to a position where the wiper 375 engages the fourteenth contact of the set 387, this path is again completed. As the switch continues to operate, this path is completed for a short interval at the beginning of each ringing cycle.

The arrangement of the coding switch and its associated apparatus is such that the operation thereof continues until a ringing cycle which has been started is completed, irrespective of whether the operating circuit for the start relay R310 is maintained completed. To this end, an alternative circuit is provided for maintaining the start relay R310 energized independently of its operating circuit. This hold circuit for R310 is prepared, at RA312, when R310 operates, is completed when the wiper 374 is moved into engagement with the second contact of the set 386, and is held completed until this wiper is moved into engagement with the thirteenth contact of the set 386. Hence, when the first ringing cycle is started, R310 is held operated until the cycle is completed. Again, when the wiper 374 is moved into engagement with the fifteenth contact of the set 386 to initiate

the second ringing cycle, this holding circuit is again completed and is held completed until the wiper noted is again moved into engagement with the first contact of the set 386. By virtue of this arrangement, it is not possible for improperly coded ringing current to be projected over a selected subscriber's line.

The release of the ringing interrupter is brought about by the removal of ground potential from C316 to cause the restoration of the start relay R310. When this relay restores, it opens, at RA311, the circuits over which the cyclically operating relays R320, R330 and R340 are energized, thereby to prevent further operation thereof. At RA312, the relay R310 opens a point in the circuit, just described, for maintaining R310 operated independently of its operating circuit. At RA313, the relay R310 opens a point in the above-traced path for applying ground potential to C315.

20

Operation of the apparatus to extend a connection to a rural subscriber's substation

Referring now more particularly to the operation of the apparatus to extend a connection from one of the regular automatic subscriber's lines, such, for example, as the line 101, to one of the substations associated with the line 600, and assuming that the line switch 100 operates to extend the connection from the calling substation A to the selector switch 120, when a predetermined digit is dialed at this substation, the selector switch noted is caused to operate automatically to select an idle one of the special connector switches in the group including the switch illustrated in Fig. 2. Assuming the switch illustrated is the first available idle switch of the selected group, when the subscriber's loop circuit is extended by way of the trunk line 121 to this connector switch, the line relay R200 operates to complete, at RA201 and RC202, an obvious circuit for energizing the slow-to-release hold relay R204. The hold relay, upon operating, removes, at RA205 and RC206, battery potential, as extended by way of the resistor 227 to RC206, from the control conductor C124 of the trunk line 121. At RA205 and RC206, ground is applied over an obvious path to the control conductor noted. Through the removal of battery potential from C124 and the substitution of ground potential, the connector switch illustrated is marked as busy, thereby to prevent its seizure by another of the selector switches on another call to one of the rural lines. At RA208 and RC209, the relay R204 prepares a point in the pulsing circuit, traced hereinafter, for energizing the slow-to-release relay R210 and the vertical magnet 297 in series. This circuit is completed when R200 restores at the beginning of the first impulse of the second digit dialed at the calling substation A and extends from ground at RA201 by way of RC203, RA208, RC209, the off-normal springs 269 and 268, the winding of R210, the contact springs 298, and through the winding of the magnet 297 to battery. Upon being energized over the above-traced circuit, the magnet 297 attracts its associated operating armature to step the wipers embodied in the switching mechanism 244 one step vertically or to a position opposite the first level of bank contacts. During this first step taken by the wipers, the off-normal springs 265 are moved to the off-normal position to interrupt, at the springs 268 and 269, the above-traced impulsive circuit and to prepare, at the springs 269 and 269', an alternative impulsive circuit. This

latter circuit is completed upon the operation of R210, which occurs simultaneously with the operation of the magnet 297. At the springs 267 ground is applied to the ringing interrupter start conductor C316, thereby to initiate the operation of the ringing interrupter in the manner pointed out above. At the beginning of the second impulse dialed at the calling substation A, the above noted alternative impulsing circuit is completed. Specifically, this circuit extends from ground at RA201 by way of RC203, RA208, RC209, the off-normal springs 269 and 269', RA211, RC213, the winding of R210, the springs 298 and through the winding of the magnet 297 to battery. When energized over the above-traced circuit, the magnet 297 again attracts its associated operating armature to cause the wipers of the mechanism 244 to be stepped a second step vertically or to a position opposite the second level of bank contacts. Thereafter, the magnet 297 is energized once for each impulse of the second digit dialed at the calling substation so that, at the conclusion of this digit, the switch wipers embodied in the mechanism 244 stand in a position opposite the level of bank contacts terminating the lines of the group including the called line 600. During this series of impulses, the relays R204 and R210 are held operated due to the slow-to-release characteristics thereof. At the end of the second digit dialed at the calling substation, the line relay R200 is held energized for a sufficient time interval to permit R210 to restore. This relay, upon restoring, opens at RA211 and RC213, a point in the alternative impulsing circuit over which R210 and the magnet 297 were energized in series and prepares, at RA211 and RC212, a circuit for energizing the slow-to-release relay R220 and the rotary magnet 295 in series.

The last-mentioned circuit, namely that over which R220 and the rotary magnet 295 are energized, is completed when the line relay R200 restores at the beginning of the first impulse of the third digit dialed at the calling substation. This circuit extends from ground at RA201 by way of RC203, RA208, RC209, the off-normal springs 269 and 269', RA211, RC212, RA215, the winding of R220, RA231, RC232, the springs 296 and through the winding of the magnet 295 to battery. When energized over the above-traced circuit, the magnet 295 attracts its operating armature to cause the wipers of the mechanism 244 to be stepped from vertical normal into engagement with the first set of contacts in the selected level of bank contacts. The relay R220, upon operating, completes, at RA221, a path short-circuiting the armature RA215 of the busy relay R214, thereby to prevent the above-traced impulsing circuit from being opened when the wipers of the switch mechanism 244 are being moved over contact sets terminating busy lines. At RA224 and RC225, the relay R220 opens a point in the circuit, traced hereinafter, for energizing the ringing relay R230 and, at RA224 and RA222, it prepares a test circuit, traced hereinafter, over which the busy relay R214 may be energized. The rotary magnet 295 is energized once during each additional impulse of the third digit dialed at the calling substation so that, at the conclusion of the third digit, the wipers of the mechanism 244 are left standing in engagement with a set of contacts terminating the called line 600. As indicated above and pointed out with greater particularity herein-after, two operating positions are provided for

each of the subscribers' lines. Thus, if the wipers 245 to 248, inclusive, are stepped into engagement with either the fifth or sixth set of bank contacts in the level illustrated, the connector switch will be connected to the called line 600. Obviously, the one of these two sets selected will depend upon the number of impulses making up the third digit. For example, if the number of impulses in this digit is five, the switch wipers will be rotated into engagement with the contact set including the contacts 245' to 248', inclusive. On the other hand, if this digit comprises six impulses, the switch wipers will be rotated into engagement with the sixth set of contacts. The particular reason for providing two operating positions of the switch for each subscriber's line is pointed out in detail herein-after.

With the wipers of the mechanism 244 standing in one of the two positions corresponding to the called line 600, the succeeding operation of the apparatus depends upon whether the called line is idle or busy. Before describing the operation of the apparatus resulting when either one of the two conditions noted prevails, brief reference will be made to the arrangement for preventing any possibility of false operation on the part of the wipers of the mechanism 244 and for preventing any noise from being introduced in the talking circuit extending by way of these wipers. To this end, each of the two operating magnets 295 and 297 is so connected and arranged that the speed of the respective associated operating armatures is reduced at the end of each stroke thereof and when they approach their respective oppositely disposed pole faces. More specifically, the armature controlled springs 298 associated with the magnet 297 are arranged normally to short-circuit a resistor 297' and are also arranged to be controlled by a second and relatively light armature, not shown, carried by the magnet 297. This second armature is so constructed and arranged as to operate to open the springs 298 before the main operating armature of the magnet completes its movement. As a result, the initial energizing path for the magnet 297 is by-passed around this resistor. When energized, however, the magnet 297 attracts the armature controlling the springs 298 to open the path short-circuiting the resistor 297', thereby to reduce the energization of the magnet and cause the speed of the operating armature associated with this magnet to be reduced before the end of its stroke. Thus, the shock incident to the completion of the stroke of the armature is materially reduced, thereby eliminating any possibility of the wipers being falsely operated more than one step and minimizing the vibration of these wipers. An identical arrangement, including the contact springs 296 and the resistor 295', is provided in association with the rotary magnet 295 for the same purpose.

Continuing now with the operation of the apparatus which occurs following the selection of the called line 600, and assuming that the called line is busy at the time it is selected, this condition is indicated by the presence of ground potential on the control conductor C603. When, therefore, the wiper 247 is moved into engagement with the contact 247', a circuit is completed for energizing the busy relay R214, this circuit extending from ground as applied to C603 by way of the contact 247', the wiper 247, RA224, RA222, RA236 and through the winding

of R214 to battery. When the busy relay R214 operates, it prepares, at RA216 and RC218, a holding circuit for itself, which circuit is completed upon the subsequent restoration of the slow-to-release relay R220 shortly following the end of the third digit, and extends from ground at RC206' by way of RA205, RA216, RC218, RC223, RA222, RA236 and through the winding of R214 to battery. At RA215, the busy relay 5 opens a point in the operating circuit for R220, thereby to prevent further impulses dialed at the calling substation from effecting operation of R220 and the ringing code selecting switch 280. At RA219, the relay R214, upon operating, completes a path for conducting busy tone 10 current by way of the established subscriber's loop circuit through the receiver at the calling substation. This path extends from one side of the busy tone source as connected to C227 by 15 way of RA238, RA219, the condenser 249, one side of the subscriber's loop circuit, the receiver at the calling substation, and back over the other side of the subscriber's loop circuit and the upper winding of R200 to the other terminal of the 20 busy tone current source. The resulting operation of the receiver at the calling substation gives an audible indication identifying the called line as busy. Following the operation of the busy relay R214, no further operation of the apparatus 25 occurs until the partially completed connection is cleared out.

Upon receiving busy tone, the calling subscriber may initiate the release of the operated switch train by restoring his receiver to its hook 30 to cause the restoration of the line relay R200. This relay, upon falling back, opens at RA201 and RC202, a point in the operating circuit for the hold relay R205. When the hold relay restores, after an interval, it removes, at RA205 35 and RC206', ground from the control conductor C124, thereby to cause the release of the selector switch 120 and the line switch 100 in the usual manner. At RA205 and RC206, battery is substituted for ground on the control conductor C124, to mark the trunk line 121 as idle. The hold relay, upon restoring, also opens, at RA205 and RC206', a point in the previously traced holding circuit for the busy relay R214, causing this relay to restore. At RA208 and RC207, the 40 hold relay completes a circuit for energizing the release magnet 239, this circuit extending from ground at RA201 by way of RC203, RA208, RA207, the off-normal springs 266, and through the winding of the magnet 239 to battery. The resulting 45 operation of the release magnet causes the wiper carriage structure of the switching mechanism 244 to be restored to vertical and horizontal normal in the usual manner. When this occurs, the off-normal springs 265 are moved to the normal position to open, at the springs 50 266, a point in the operating circuit for the release magnet. At the springs 267, ground is removed from the ringing interrupter start conductor C316, thereby to cause the operation of this switch to be arrested providing none of the other special connector switches associated with the interrupter switch are operated. With the apparatus in this condition, the partially established connection is completely released and the 55 switches involved therein are in readiness for further use.

Assuming now that the called line 600 is idle instead of busy at the time it is selected by the connector switch shown in Fig. 2, this condition 60 of the switch is identified by the application of

battery potential to the control conductor C603 thereof through the winding of R400. When, therefore, the wiper 247 is operated into engagement with the contact 247' terminating the conductor C603, a circuit is prepared for energizing the relay R230. This circuit is completed upon the subsequent restoration of R220 and extends from ground at RC206' by way of RA205, RA216, RC217, the lower winding of R230, RC225, RA224, the switch wiper 247, and the contact 247' to 10 battery as applied to C603. The relay R230 operates, when its lower winding is energized over the above-traced circuit, and completes, at RA235, a holding circuit for itself, this circuit extending from ground on RC206', by way of 15 RA205, C124, RA234 and through the upper winding of R230 to battery. At RA234, the relay R230 applies ground to the switch wiper 247, thereby to complete a circuit for energizing the cut-off relay R400 associated with the line 600. Specifically, this circuit extends from ground at RA234 by way of the switch wiper 247, the contact 247', C603, and through the winding of R400 to battery. The application of ground to the control conductor C603 of the line 600 serves to mark 20 this line as busy in the bank contacts of the various other connector switches to which it extends. When R400 is energized over the circuit just traced, it opens, at RA402, a point in the circuit, traced hereinafter, for energizing the 25 lower winding of the alternating current relay R405, and, at RA401, it disconnects the upper winding of this relay from across the conductors of the line 600. At RA403, the relay R400 extends ground as applied to C603 to the particular bank 30 contacts of the various finder switch contact banks, which correspond to the line 600, thereby to preclude any of these switches from inadvertently seizing the line 600 during the operation thereof to select another of the rural lines 35 40 having a calling condition created thereon.

At RA238, the relay R230, upon operating, opens a point in the above-traced path for applying busy tone current to the loop extending to the calling subscriber's substation and, at RA237, it prepares a circuit, traced hereinafter, for energizing the first relay R250 of the group of ringing control relays R250, R260 and R270. At RA239, the relay R230 completes a circuit for energizing R240, this circuit extending from 45 ground as applied to the bank contact 248' by way of the switch wiper 248, RA239, and through the winding of R240 to battery. The resulting operation of R240 to move RA241 into engagement with RC243 insures that the selected one 50 of the ringing current conductors will be included in the group terminating at the bank contact set 281 of the code selector switch 280. In this connection, it will be understood that, had the wipers of the mechanism 244 been operated 55 into engagement with the sixth set of contacts of the selected level or to the second operating position corresponding to the called line 600, no circuit would have been available for energizing R240 and, hence, this relay would not have been 60 energized following the operation of R230. With R240 deenergized, the ringing current conductor ultimately selected would necessarily be one of the conductors terminating at the contacts forming the set 282 of the switch 280 because, in such 65 case, RA241 would remain in engagement with RC242, which contact is connected to the switch wiper 284.

At RA231 and RC233, the relay R230, upon operating, prepares an impulsive circuit extending 70 75

to the operating magnet 228 of the switch 280. With the apparatus in this condition, the connector switch is conditioned to respond to the fourth and final digit dialed at the calling substation A. At the beginning of the first impulse of this digit, the above-noted circuit for energizing the operating magnet 228 is completed, this circuit extending from ground at RA201 by way of RC203, RA208, RC209, the off-normal springs 269 and 269', RA211, RC212, RA215, the winding of R220, RA231, RC233, and through the winding of the magnet 228 to battery. The resulting operation of the magnet 228 causes the switch 280 to be conditioned to step the wipers 283 and 284 10 to the first off-normal position or into engagement with the first contacts of their respective associated sets 281 and 282. When the relay R220 operates, it completes, at RA221, the above-noted path for short-circuiting the armature 20 RA215 of the busy relay R214. At the end of the first impulse and when R200 restores to open the above-traced operating circuit for the magnet 228, the wipers 283 and 284 are stepped to the first off-normal position to select the two ringing 25 conductors terminating at the respective first contacts of the sets 281 and 282. When this first step is taken by the wipers of the switch, the off-normal springs 285 are moved to the off-normal position. At the springs 286, a circuit, traced 30 hereinafter, is prepared for energizing the release magnet 229 and, at the springs 287, a circuit is prepared for energizing the busy relay R214, this latter circuit being traced hereinafter and being held open at the operated armature 35 RA226 of the relay R220. For each succeeding impulse of the fourth digit dialed at the calling substation, the magnet 228 operates to cause the associated wipers 283 and 284 to be stepped one 40 step so that, at the conclusion of the digit, one of the wipers 283 and 284 will be standing in engagement with a contact terminating a ringing current conductor having impressed thereon coded ringing voltage of the particular code which corresponds to the called substation E. 45 As pointed out above, in the particular case under consideration and with R240 operated, the coded ringing current must be conducted to the called line 600 by way of one of the ringing current conductors terminating at the contacts 50 forming the set 281. If it be assumed that the coded signal identifying the substation E corresponds to the code of the ringing voltage applied to the fourth conductor terminating at the contact set 281, the final digit dialed at the calling 55 substation will necessarily comprise four impulses so that, at the conclusion of the digit, the wipers 283 and 284 will be left standing in engagement with their respective associated fourth contacts. 60 Shortly following the conclusion of the fourth digit dialed at the substation A, the relay R220 restores to open, at RA221, a point in the path short-circuiting the armature RA215 of the busy relay R214 and to complete, at RA226, the above- 65 mentioned circuit for energizing the busy relay. This circuit extends from ground at the lower one of the off-normal springs 287 by way of the upper spring of this set, RA226, and through the winding of R214 to battery. The relay R214, 70 upon operating, opens, at RA215, a point in the circuit for energizing R220 and the magnet 228 in series, thereby to prevent any further operation of the impulsing device provided at the calling substation from effecting further operation of 75 the ringing code selecting switch 280. At RA219,

the busy relay prepares a point in the above-traced path for applying busy tone to the loop extending to the calling substation. This path is, however, now open at the operated armature RA238 of the relay R230. At RA219', the relay 5 R214 prepares a circuit for energizing R250, which relay functions to complete a path for applying ringing voltage to the talking conductors of the line extending to the called substation E. The circuit for energizing R250 is completed 10 when the ringing interrupter switch is operated to a position to start a new ringing cycle, at which time a ground pulse is applied to C315. Thus, if R214 operates just prior to the operation of the wipers of the interrupter switch into 15 engagement with their respective associated first contacts, this circuit is completed when the wiper 375 is moved into engagement with its associated first contact and extends from ground at the wiper 375 by way of RA313, C315, RA219', RA237, 20 RA255, RC256 and through the lower winding of R250 to battery. The relay R250 now partially operates to complete a closed circuit for short-circuiting its upper winding, this circuit extending from ground as applied to the control conductor C124 by way of RA254, the upper winding of R250, RC256, RA255, RA237 and RA219' back to ground on C315. When ground is subsequently removed from C315 through the movement of the wipers of the switch 300 out of engagement 25 with their respective associated first contacts, the above-traced short-circuiting path is opened and the two windings of R250 are energized in series, causing the relay R250 to complete its 30 operation. Upon fully operating, R250 opens, at 35 RA255 and RC256, a point in the above-traced circuit for energizing its lower winding and prepares, at RA255 and RA256', a circuit for energizing the lower winding of R260. At RA251 and 40 RA252, a path is completed for projecting ringing current over the conductors of the called line 600. In the present assumed case, wherein the code identifying the called substation E corresponds to that of the voltage applied to the ringing current conductor 21, the path of this current extends from the upper terminal of the secondary winding 328 by way of RC333, RA332, the switch wiper 371 of the wiper 372, the conductor 21, the wiper 283, RC243, RA241, RA252, RC276, RA275, the wiper 246, the contact 246', the line conductor C601, the condenser 604, the windings of 45 the signal device 603, the switch springs 621 and 628, C602, the contact 245', the wiper 245, RA251 and RA271 to the grounded terminal of the secondary winding 328 at RC273. It will be understood 50 that portions of this current are by-passed through the signal devices provided at each of the other stations associated with the line 600. Due to the particular coding of the current, however, the subscriber at the substation E is informed 55 that his substation is being called and the other subscribers are informed that the call is not intended for their respective substations. A portion of the ringing current is by-passed by way of the condenser 279, RA253 and through the 60 repeater windings 294 and 293 in series to ground at RC273 to cause ring-back tone current to be impressed on the loop extending to the calling subscriber's substation, thereby to indicate to the calling party that the ringing operation is being 65 performed.

As indicated above, one feature of the present invention pertains to the arrangement of the apparatus whereby ringing current is only applied to the called line for a predetermined number of 75

ringing cycles. Thus, at the beginning of the second ringing cycle, when ground is again applied to C315 by the interrupter switch 300, the relay R260 is caused partially to operate through the energization of its lower winding over a circuit extending from ground on C315 by way of RA219', RA237, RA255, RC256', RA262, RC264, and through the lower winding of R260 to battery. With its lower winding energized over the above-traced circuit, the relay R260 partially operates to complete, at RA261, a closed circuit for short-circuiting its upper winding, this circuit extending from ground on the control conductor C124 by way of RA261, the upper winding of R260, RC264, RA262, RC256', RA255, RA237, and RA219' back to ground on C315. When ground is thereafter removed from C315 through the continued operation of the interrupter switch 300, the above-traced short-circuiting path is interrupted and the relay R260 fully operates to open, at RA262 and RC264, a point in the above-traced circuit for energizing its lower winding and to prepare, at RA262 and RC263, a circuit for energizing R270. This last-mentioned circuit is completed after the second ringing cycle is ended and at the beginning of the third ringing cycle when ground is again applied to the control conductor C315. In this case, the circuit for energizing R270 extends from ground on C315 by way of RA219', RA237, RA255, RC256', RA262, RC263, RA278' and through the winding of R270 to battery. When energized over the above-traced circuit, R270 operates to complete, at RA278, a holding circuit for itself, this circuit extending from ground as applied to C124 by way of RA278 and the winding of R270 to battery. At RA278', the relay R270 open-circuits the pick-up or control lead C315, thereby to permit the ground pulses impressed on this lead to be effective in controlling others of the connector switches in the group including the switch illustrated in Fig. 2. The relay R270 opens, at RA271 and RA275 and their respective associated contacts RC273 and RC276, two points in the above-traced path over which ringing current is projected out over the called line 600 and also two points in the path by way of which ring-back tone currents is impressed on the loop extending to the calling subscriber's substation. At RA271 and RA275 and their respective associated contacts RC274 and RC277, the conductors of the trunk line incoming to the connector switch are connected through to the conductor C601 and C602 of the called line, thereby to complete the connection to the called line. More particularly, the talking circuit is completed when the call is answered at the substation E. Thus, when the receiver 615 is removed from its hook, the spring 621 is moved into engagement with its associated contact springs 626 and 627 and the springs 625 are closed. With the switch hook 620 in this position, the receiver 615 is connected across the conductors of the line 600 and the transmitter 614 is included in a closed circuit by means of which generated voice frequency currents may be impressed on the line 600 through the transformer 610. In this connection, it is pointed out that the battery 613 is utilized in generating voice frequency currents at the called substation, whereas talking battery is supplied to the loop extending to the calling substation by way of the windings of the line relay R200.

The release of a connection as established in the manner described above to the substation E is entirely under the control of the calling party.

Thus, if the receiver 615 is restored to its hook before the connection is cleared out at the calling substation, the only result effected thereby is the disconnection of this receiver from across the conductors of the line 600 and the interruption of the closed circuit including the transmitter 614. When, however, the calling party restores his receiver to its hook to open the loop circuit by way of which the line relay R200 is held operated, this relay restores to open, at RA201, the operating circuit for the hold relay R204. When R204 restores, ground is removed from the control conductor C124 to cause the restoration of the selector switch 120 and the line switch 100 in the manner pointed out above and to open the respective holding circuits for R230, R250, R260 and R270. The relay R230, upon restoring, interrupts, at RA234, the previously traced circuit for energizing the cut-off relay R400, causing the last mentioned relay to restore. When the hold relay restores, the above-traced circuit for energizing the release magnet 238 is completed. The resulting operation of this magnet causes the wiper carriage structure of the switching mechanism 244 to be restored to normal in the manner pointed out above, at which time the off-normal springs 265 are returned to the normal position. When this occurs, the operating circuit for the start relay R310 embodied in the control apparatus for the interrupter switch 300 is opened and, assuming that none of the other special connector switches are operated, this interrupter switch is restored to normal in the manner pointed out above. When the hold relay R204 falls back, a circuit is also completed for energizing the release magnet 229 embodied in the code selector switch 280, this circuit extending from ground at RA201 by way of RC203, RA208, RC201, the off-normal springs 286 and through the winding of the magnet 229 to battery. The resulting operation of this magnet causes the wipers of the switch 280 to be returned to normal, at which time the off-normal springs 285 are restored to normal to open, at the springs 286, the operating circuit for the release magnet 229. When the springs 287 are opened, the operating circuit for R214 is interrupted, causing this relay to restore. Thus, the connector switch is entirely released and is in readiness for further use.

Operation of the apparatus to extend a connection from a rural subscriber's substation to an automatic subscriber's substation

Referring now more particularly to the operation of the apparatus to set up a connection between the line 600 and the line 101 on a call originating at the substation E, the call is initiated through the operation of the magneto generator 605 provided at the calling substation. Before operating this generator, however, the calling party should listen in on the line to determine whether or not the line is busy in connection with another call. This may be done by moving the hook latch 624 to a position for holding the contact springs 625 out of engagement and thereafter removing the receiver 615 from its hook to complete a path by way of which this receiver is connected across the conductors of the line 600. Specifically, this path extends from C601 by way of the impulsive springs 631, the transformer winding 612, the receiver 615, the condenser 616, and the switch springs 627 and 621. It will be noted that this path is interrupted for direct current by the condenser 75

618. The purpose of inserting this condenser in the path is to prevent a short-circuit from being placed across the conductors of the line which might interfere with the dialing operation being 5 performed at another of the substations associated with the line at the time the line is challenged at the substation E. More particularly, the arrangement of the apparatus at each of the other stations is identical with that of the apparatus provided at the substation E, and it will be apparent that if the impulsing device at the last-mentioned station were being operated to deliver impulses to the switching equipment provided in the exchange and a short-circuit were 10 placed across the conductors of the line 600, the call would either be falsely routed to the wrong substation or would fail entirely.

After the line is challenged and when the magneto generator 605 is operated, alternating current is projected by way of the springs 606 and the line conductors C601 and C602 through the upper winding of the alternating current relay R405, causing this relay to operate. Upon operating, R405 completes, at RA407, a circuit for 20 energizing its lower winding in series with the start relay R520 provided in the common equipment 500, this circuit extending from ground at the lower terminal of the winding of R520 by way of this winding, C522, RA402, RA407, and 25 through the lower winding of R405 to battery. At RA406, the relay R405 opens a point in the path over which its upper winding is energized and, at RA408, it completes a path for marking the calling line 600 in the bank contacts of the 30 finder switches to which this line extends. More particularly, battery is extended through the winding of R400 and by way of RA408 to the fifth contact of the contact set 494 in the finder switch 490 and to the corresponding contacts of 35 the other finder switch banks.

The common equipment 500 operates in a manner such that the allotter switch provided therein operates to a position corresponding to an idle one of the finder-repeater links immediately after an assigned link has been caused to seize a calling line. Assuming, for example, that the wipers of this switch are standing in the position corresponding to the link illustrated, that is, in engagement with their respective associated 45 tenth contacts, at the time the start relay R520 operates, this relay initiates the operation of the finder portion of the link to search for and seize the calling line 600. More particularly, when R520 operates, it completes, at RA521, a circuit 50 for energizing the winding of R540 in series with the winding of the operating magnet 511, this circuit extending from ground at RA521 by way of the winding of R540, RA546, RA555, the armature 512 and through the winding of the magnet 511 to battery. Due to the relatively high resistance of the winding of R540, the magnet 511 55 does not operate. Hence, the wipers of the allotter switch are maintained in the position corresponding to the link illustrated. The relay R540, however, operates to complete, at RA544, a circuit for energizing the operating magnet 499 of the finder switch 490 and to prepare, at RA545, a circuit for energizing R530. At RA541, the relay R540 prepares a point in the holding circuit 60 for R550 and, at RA543, it prepares a point in the circuit for energizing the upper windings of R550. At RA546, the relay R540 opens a point in the path normally short-circuiting the resistor 65 556 so that this resistor is included in the series

circuit over which the relay R540 is held energized.

The above-mentioned circuit over which the magnet 499 is energized extends from ground at RA552 by way of RC554, RA544, RA531, the 5 wiper 507, the tenth contact of the set 502, C524 and the winding of the magnet 499 to battery. When energized over this circuit, the magnet 499 advances the wipers of the switch 490 one step and attracts its armature 499' to complete the 10 above-mentioned circuit for energizing R530, this circuit extending from ground at the contact associated with the armature 499' by way of this armature, C523, the tenth contact of the set 501, the wiper 506, RA545, and through the winding 15 of R530 to battery. When R530 operates, it interrupts, at RA531, the above-traced circuit for energizing the magnet 499, causing this magnet to restore its armature 499' to interrupt the operating circuit for R530. When R530 restores, 20 it again completes, at RA531, the circuit for energizing the magnet 499, causing this magnet to operate to advance the wipers of the switch 490 a second step and to again complete the operating circuit for R530. The interrelated operation 25 of the magnet 499 and R530 continues until such time as the wipers are moved to the position corresponding to the calling line 600. Assuming that the movement of the wipers is started with these wipers occupying the position indicated in the drawings, five steps on the part of the switch 490 will be required before these wipers are moved into engagement with the contacts of the set terminating the line 600. When the wiper 498 engages the fifth or marked contact of 30 the set 494, a circuit is completed for energizing the upper winding of the slow-to-release relay R550 in series with the winding of R400, this circuit extending from ground at the lower terminal of the upper winding of R550 by way of 35 this winding, RA543, the wiper 508, the tenth contact of the set 503, C525 the wiper 498, the fifth contact of the set 494, RA408 and through the winding of R400 to battery. When its upper winding is energized over the above-traced circuit, R550 operates to complete, at RA551, a holding 40 circuit for itself, this circuit extending from ground at RC542 by way of RA541, RA551 and the lower winding of R550 to battery. At RA552 and RC554, the relay R550 opens a point in the 45 above-traced operating circuit for the magnet 499, thereby to arrest the interrelated operation of this magnet and R530. At RA552 and RC553, the relay R550 completes a circuit for energizing the switching relay R410, this circuit extending 50 from ground at RA552 by way of RC553, the wiper 509, the tenth contact of the set 504, C526 and through the winding of R410 to battery. When R410 operates, it switches the subscriber's loop circuit through to the repeater portion 55 of the link and completes, at RA414', a circuit for fully energizing the cut-off relay R400, this circuit extending from ground at RA414' by way of the wiper 498, the fifth contact of the set 494, RA408 and through the winding of R400 to battery. The cut-off relay R400 operates when energized over the above-traced circuit extending from ground at RA414' and, upon operating, completes, at RA403, a holding circuit for itself, 60 which circuit extends from ground at RA414' by way of the switch wiper 498, the fifth contact of the set 494, RA403 and the winding of R400 to battery. It will be noted that, when R410 operates, ground from RA414' is extended to the control conductor C603 of the line 600, thereby 65 70 75

to mark this line as busy in the bank contacts of the connector switches to which it extends.

At RA402, the relay R400 opens a point in the above-traced circuit for energizing the lower winding of R405 and the start relay R520 in series, causing both of these relays to restore, assuming that none of the other rural lines are waiting to be assigned finder-repeater links. If a second calling line is waiting for a link at the time R400 operates, the start relay R520 will be held energized and only R405 will restore. At RA401, the relay R400 holds the upper winding of R405 disconnected from across the talking conductors of the line 600. Assuming that the start relay R520 restores, it opens, at RA521, a point in the above-traced operating circuit for R540, causing this latter relay to restore to open, at RA541, the holding circuit for R550. When R550 restores, a point is opened in the above-traced operating circuit for R410. Before R550 falls back, however, and during the sequence of operations just described, R560 is caused to operate to complete a holding circuit for R410.

Thus, immediately the subscriber's loop is extended to the repeater portion of the link, a circuit is completed for energizing the line relay R415, this circuit extending from ground at the fifth contact of the set 492 by way of the wiper 496, RA413, the repeater winding 474, RA414, the switch wiper 497, the fifth contact of the set 493, C601, the impulsive springs 631, the transformer winding 612, the receiver 615, the contacts 625, 627 and 621, C602, RA406, the fifth contact of the set 491, the wiper 495, RA412, the repeater winding 473, and through the winding of R415 to battery. The relay R415 operates, when energized over the above-traced circuit, to complete, at RA419, an operating circuit for R420, this latter circuit extending from ground at RA431 by way of RC432, RA419, and the winding of R420 to battery. The relay R420 now operates to complete a circuit for energizing the slow-acting relay R430, this circuit extending from ground at RA421, by way of RC422 and the winding of R430 to battery. At RA424, the relay R420 completes a holding circuit extending by way of the resistor 424' for maintaining itself operated independently of the hold relay R430. When the last-mentioned relay operates, it opens, at RA431 and RC432, a point in the above-traced operating circuit for R420, prepares, at RA434, a point in the circuit, traced hereinafter, for energizing R450, and completes, at RA435, a circuit for energizing R560, which latter circuit extends from ground at RA435 by way of RA581 and the upper winding of R560 to battery. When R560 operates, it completes the above-noted holding circuit for R410, this circuit extending from ground at RA561 by way of RC563, C526 and the winding of R410 to battery. As indicated above, the arrangement of the apparatus is such that this holding circuit is completed through the operation of R560 before R550 restores to open the operating circuit for R410. When R560 operates, it also completes a holding circuit for itself, this circuit extending from ground at RA465 by way of RA582, RA566, and the lower winding of R560 to battery. At RA564, the relay R560 prepares a circuit for energizing the pulse responsive relay R570 and, at RA565, it applies ground to the tenth contact of the set 505, thereby to mark the finder-repeater link illustrated as busy in the allotter switch provided in the common equipment 500.

75 In the event the start relay R520 remains op-

erated following the operation of R400, the two relays R540 and R550 are held operated until R560 operates. When the last-mentioned relay operates, the winding of R540 is short-circuited at RA565, causing R540 to restore to open, at RA541, the holding circuit for R550. When R550 restores, it completes a circuit for energizing the operating magnet 511 of the allotter switch, this circuit extending from ground at RA565 by way of the wiper 510, RA546, RA555, 10 the circuit-interrupting contacts associated with the armature 512, and the winding of the magnet 511 to battery. The magnet 511, upon being energized over this circuit, attracts its armature to open its operating circuit and to step the wipers 15 of the allotter switch one step or into engagement with the contacts of the set corresponding to the next finder-repeater link. If this next link is busy, the contact of the set 505 which corresponds thereto will also have ground potential 20 impressed thereon so that the magnet 511 will again be energized, causing the wipers of the allotter switch to be moved a second step. The stepping operation of the switch continues until such time as the wiper 510 encounters a contact 25 corresponding to an idle one of the finder-repeater links, this idle condition being indicated by the absence of ground potential on the contact corresponding thereto. Thus, when the link illustrated is idle, R560 is deenergized so that the 30 tenth contact is open-circuited. When, therefore, the allotter switch is operated to a position corresponding to an idle link, no further circuit is available for energizing the magnet 511, and the stepping operation of the switch is arrested. 35

Following the operation of R415, R420, R430 and R560, the control apparatus embodied in the repeater portion of the link is conditioned to respond to the first series of impulses dialed at the substation E.

As pointed out in the introductory portion of the specification, the arrangement of the repeater portion of each link is such that a preliminary or prefix digit is required to cause a loop circuit to be established between the repeater portion 45 of the link and its associated line switch. More particularly, with the link illustrated, the relay R460 is operative to connect the conductors of the trunk line 125 across the secondary windings of the repeater coil 472 only following the dialing 50 of a digit comprising ten impulses at a calling substation on a line to which the link has been allotted for use. An impulse correcting relay network is provided such that the character of each impulse repeated over the trunk line 125 55 is, within limits, independent of the character of the corresponding impulse dialed at the calling substation. At the beginning of the first impulse dialed at the calling substation E, the above-traced loop circuit over which R415 is energized 60 is interrupted at the impulsive springs 631. During impulsive, the shunt springs 632 of the impulsive device 630 are moved to the off-normal position to short-circuit the receiver 615 in series with the secondary winding 612 of the transformer 610. When R415 restores in response to the interruption of the above-traced loop circuit, it opens, at RA419, the circuit over which R420 65 is held energized and completes, at RA416 and RC417, a priming circuit for itself, this latter circuit extending from ground at RA431 by way of RC433, RA416, RC417, the resistor 417' and the winding of R415 to battery. When R420 restores, it opens, at RA424, its holding circuit 70 and completes, at RA421, a circuit for energizing 75

the lower winding of R450, which circuit extends from ground at RA421 by way of RC423, RA434, RA444 and the lower winding of R450 to battery. The relay R450, upon operating, short-circuits, 5 at RA452, its upper winding, thereby to render itself slow-to-release, and completes, at RA451, an obvious multiple holding circuit for the hold relay R430. At RA454, the relay R450 completes a circuit for energizing the lower winding of 10 R440, this circuit extending from ground at RC454 by way of RA454, the resistor 456, RA425, and through the lower winding of R440 to battery. With R440 deenergized, its upper winding is short-circuited at RA443 and, hence, this relay 15 possesses a slow-to-operate characteristic. It operates, after an interval, however, to open, at RA443, the path short-circuiting its upper winding whereby it is rendered fast-to-release. At RA444, the relay R440 opens the operating circuit for R450. With R440 operated, and when 20 the line relay R415 reoperates at the end of the first pulse, a circuit is completed for again energizing R420, this circuit extending from ground at RC442 by way of RA441, RA419 and through 25 the winding of R420 to battery. The relay R420 now reoperates to complete, at RA424, its above-traced holding circuit and to open, at RA425, the operating circuit for R440, causing this latter 30 relay to restore. The restoration of R440 does not result in the recompletion of the operating 35 circuit for R450, however, since this circuit is now open at RA421 and RC423. The above-described cycle of operation and restoration of the relays R415, R420, R450 and R440 is repeated 40 for each impulse dialed at the calling substation E. Since, in the present assumed case, the preliminary digit dialed at the substation E comprises ten impulses, it will be understood that, during this digit, the cycle of operation of the 45 relays noted is repeated ten times. As indicated previously, R450 is the impulsive relay, and it will be apparent from the foregoing description that the relation between the period of deenergization and the period of energization of this 50 relay during each impulse is, within limits, independent of the relation between the corresponding periods for the line relay R415. More particularly, the restoration of R415 at the beginning of each impulse cycle initiates the operation 55 of the three relays R420, R450 and R440 to repeat the impulse, and the extent of the period during which R450 is energized depends primarily upon the slow-to-release characteristic of this relay and the slow-to-operate characteristic of R440.

During the period of each impulse when the pulsing relay R450 is operated, a circuit is completed for energizing the slow-to-release relay R475 and the operating magnet 485 of the switch 60 480 in parallel, this circuit extending from ground at RA453 by way of RA464 to RA471, where it divides, one branch extending through the winding of R475 to battery and the other branch extending through the winding of the magnet 485 to 65 battery. The relay R475 operates at the beginning of the first impulse repeated by R450 and remains operated during the succeeding impulses and until the digit is completed. At its armature RA476, this relay opens a point in the circuit, 70 traced hereinafter, for energizing R470. Obviously, at the end of the first and each succeeding impulse, the above-traced circuit for energizing the magnet 485 is opened. Each time this magnet is deenergized following its energization, it 75 steps the wipers 483 and 484 one step. Since the

preliminary digit comprises ten impulses, the wipers noted will be stepped to the tenth off-normal position or into engagement with their respective associated tenth contacts. At the beginning of the first step taken by the wipers of the switch 480, the off-normal springs 486 are closed to prepare a circuit for energizing the release magnet 487. This circuit is held open for the duration of the call, however, through the continued energization of R560. 10

If it be assumed that the wipers of the switch 480 are successfully operated into engagement with their respective associated tenth contacts in response to the dialing of the preliminary digit at the calling substation E, shortly following the 15 restoration of R450 at the conclusion of the digit, the relay R475 restores, but without effect. Immediately the wiper 483 is moved into engagement with the tenth contact of the set 481, a circuit is completed for energizing R460, this circuit extending from ground at the wiper 483 by way of its associated tenth contact and the winding of R460 to battery. This relay, upon operating, opens, at RA464, a point in the above-traced circuit for energizing the magnet 485 and the relay R475 in 20 25 accordance with the operation of the pulsing relay R450. At RA469, the relay R460 completes an alternative holding circuit for R560, this circuit extending from ground at RA435 by way of RA469 and the upper winding of R560 to battery. At RA465, the relay R460 opens a point in the holding circuit for R570 and the initial holding circuit for R560. Through this operation, the link release relay R588 is prevented from operating to initiate the release of the link in the manner pointed out more in detail hereinafter. At RA461 and RC462, the relay R460 opens a point in the path, described hereinafter, for connecting the artificial leak impedance element 411' across the conductors of the line 600. 30 35 40

When the relay R460 operates, it also completes a loop circuit to the line switch 130 terminating the trunk line 125. More particularly, this relay connects a bridge across the line conductors of the trunk 125, this bridge extending from the 45 trunk line conductor C126 by way of RC467, RA466, RA455, the repeater winding 479, the resistor 456, the repeater winding 478 and RA463 to the opposite trunk line conductor C127. When this loop circuit is completed, the line switch 130 50 operates in the usual manner to extend the connection to an idle one of the selector switches. Assuming, for example, that the selector switch 140 is the first idle switch available, when the loop circuit is extended thereto through the operation 55 of the line switch 130, it is conditioned to respond to the second series of impulses dialed at the calling substation E.

During the dialing of the second digit at the calling substation, the four relays R415, R420, 60 R450 and R440 respond in the exact manner pointed out in detail above; that is, R450 operates once during each impulse. Each time R450 operates, it opens, at RA455, the loop circuit as extended to the selected selector switch 140, which 65 selector switch responds to the repeated impulses by elevating its wipers in the usual manner to a position opposite the level of bank contacts terminating the trunk lines extending to the connector switches having access to the called line 101. 70 Thereafter, the selector switch operates automatically to select an idle one of the connector switches in the selected group. Assuming that the connector switch 150 is the first available 75 switch in the selected group, when the wipers of

the selector switch 140 are moved into engagement with the contacts terminating the trunk line extending to this connector switch, the loop circuit is automatically extended to the last-mentioned switch, causing this switch to be conditioned to respond to the impulses making up the third and four digits dialed at the calling substation E. When the third digit is dialed at the calling substation, the connector switch 150 responds to select the group of ten lines including the called line 101, it being again pointed out that the impulses of this digit are repeated to the operated connector switch 150 through the interrelated operation of the relays R415, R420, R450 and R440. Following the selection of the ten-line subgroup, and when the fourth digit is dialed at the substation E, the connector switch 150 operates to select the called line 101. In order to insure a faithful response of the seized switches 140 and 150, or of other switches respectively corresponding thereto, to the operation of the pulsing relay R450, all such switches are preferably equipped with impulse correcting networks similar to that including the three relays R420, R450 and R440, described in detail above. The manner in which the connector switch 150 functions to test the called line to determine its idle or busy condition, to return busy tone over the established loop to the calling substation in case the called line is busy at the time it is selected, and to apply ringing current to the called line in case the line is idle, is identical to that described above with reference to the connection established between the substations A and B on a call initiated at the substation A. Assuming that the called line is idle at the time it is selected by the switch 150, the desired conversational circuit is completed when the call is answered at the called substation A.

40 The release of the operated switches 150, 140 and 130 and of the operated finder-repeater link is preferably solely under the control of the calling party. Thus, when the calling party restores the receiver 615 to its hook to return the springs of the hook switch 620 to normal, the loop circuit 45 over which R415 is held energized is interrupted at the springs 621 and 627. When R415 restores, it opens, at RA419, the circuit over which R420 is held energized. The last-mentioned relay now restores to open, at RA421 and RC422, the operating circuit for the hold relay R430. This hold relay, upon restoring, opens, at RA435, the hold circuit for R560. When R560 restores, it removes, at RA565, ground from the contact of the set 505 corresponding to the finder-repeater link illustrated, thereby to mark this link as idle in the bank contacts of the allotter switch. When R560 restores, it also completes a circuit for energizing the release magnet 487, this circuit extending from ground at RA561, by way of RC562, the off-55 normal springs 486 and through the winding of the magnet 487 to battery. The resulting operation of the magnet 487 causes the wipers of the switch 480 to be returned to normal, at which time the off-normal springs 486 are opened to 60 interrupt the operating circuit for the magnet 487. When, during the restoration of the switch 480, the wiper 483 is moved from engagement with the tenth contact of the set 481, the circuit over which R460 is held energized is interrupted, 65 causing this relay to restore to open, at RA463 and RA466, the loop circuit which extends through to the operated connector switch 150. The interruption of this loop circuit results in the release of the operated switches 150, 140 and 70 130 in the exact manner pointed out above with 75

reference to a call initiated at the substation A and extended to the substation B.

When R560 restores, it further functions to open, at RA561 and RC563, the holding circuit for R410, causing this relay to restore to remove, at RA414', ground from the control conductor C603 of the line 600. The removal of ground from the control conductor noted results in the restoration of R400 and, when this relay restores, it reconnects the upper winding of R405 across the line 10 conductors of the line 600 and reprepares the start circuit for energizing the lower winding of R405 in series with the start relay R520. The apparatus is now completely restored to normal and in readiness for further use. In this connection it is pointed out that the finder portion of the link is of the non-homing type; that is, the wipers of the switch 490 remain in the position to which they are operated during a line hunting operation until further operation of the switch 20 is initiated.

As pointed out in the introductory portion of the specification, one of the features of the present invention is concerned with the arrangement of the apparatus whereby a calling rural subscriber's line can only gain access to the regular automatic switching equipment provided in the automatic exchange through a predetermined operation of the dialing device at the calling substation on the calling line to transmit a predetermined series of impulses to a seized finder-connector link. It may happen that, due to a faulty condition of the line, the line relay included in the finder-repeater link operatively associated with the calling line will not respond to all of the impulses dialed at the calling substation, but only to a portion thereof. On the other hand, the calling party may, through carelessness, fail to dial the requisite number of impulses. Obviously, in either case, a false call would result if the impulses were dialed directly into one of the automatic switches included in the regular automatic switching equipment. With the arrangement illustrated, however, and wherein the prefix digit is required, none of the regular switching equipment is tied up due to either of the two causes noted. Moreover, the arrangement is such that the impulsive conditions of any calling line are tested when the control apparatus of the associated finder-repeater link is responding to the impulses of the prefix digit dialed at the calling substation. This test is achieved by connecting a leak impedance across the conductors of the calling line during the transmission of the impulses making up the prefix digit, thereby artificially to reduce the impulse transmitting efficiency of the calling line. If the line relay of the operated finder-repeater link faithfully responds to the impulses of the preliminary digit under the adverse impulsive conditions imposed by the leak impedance, this impedance is disconnected from across the line conductors during further operation of the dialing device at the calling substation, thereby to increase the impulse transmitting efficiency of the line. Thus, considering again the operation of the link illustrated to extend a connection from the substation E to the substation A on a call initiated at the first-mentioned substation, when the relay R410 operates to extend the subscriber's loop circuit through to the repeater portion of the link illustrated in Fig. 4, it not only completes the above-traced circuit including the conductors of the line 600 for energizing the line relay R415, but connects the resistor 411 in series with the two repeater windings 473 and 474 across the

line conductors C601 and C602 by completing a path extending from C601 by way of the fifth contact of the set 493, the switch wiper 497, RA414, the winding 474, RA413, the wiper 496, 5 the fifth contact of the set 492, ground, RC462, RA461, RA411, the resistor 411', the winding 473, RA412, the wiper 495, the fifth contact of the set 491 and RA406 to the opposite line conductor C602. The effect of this resistor is to simulate a 10 resistance leak directly between the conductors of the line and results in the partial energization of the line relay R415. This relay is so adjusted that it does not operate when energized through this leak path and over the priming circuit including 15 the resistor 411', but only operates when the impulsive springs 631 at the calling substation are closed. With this resistance leak present on the line and when the impulsive springs 631 are opened, the reduction in the current traversing 20 the winding of R415 is considerably less than it would be if the resistor 411' were not connected to the line. Moreover, if any other leak resistances are present on the line, due to a faulty condition of the line, the decrease in the energization of 25 R415 may be so small as not to result in the restoration of this relay. On the other hand, if the line is substantially clear of current leak paths between the conductors thereof, the relay R415 will respond in the desired manner by re- 30 storing. By properly relating the resistance value of the element 411' to the circuit constants of a line possessing reasonably good impulse transmitting properties and adjusting the relay R415 accordingly, the impulse transmission efficiency of 35 any calling one of the rural lines selected by the link may be accurately tested.

As was pointed out above, if the impulse responsive line relay R415 faithfully responds to the impulses of the preliminary digit, the minor 40 switch 480 is caused to operate to its tenth off-normal position, whereby the operating circuit for the line switching relay R460 is completed. This last-named relay, upon operating, interrupts, at RA461 and RC462, the above-traced 45 path by way of which the resistor 411' is connected across the conductors of the calling line. As a consequence, the decrease in the energization of R415 during the open circuit period of each impulse of each digit following the first digit 50 is substantially greater than the decrease occurring during the open circuit periods of the impulses in the first digit or, stated otherwise, the responsiveness of R415 to impulses dialed at the calling substation is enhanced. If the line relay R415 does not faithfully respond to the impulses 55 of the preliminary digit, the required ten impulses will not be delivered to the switch 480 and the wipers of this switch will not be operated to the tenth off-normal position at the conclusion 60 of the digit. Hence, when R475 restores at the end of the preliminary digit, a circuit is completed for energizing R470, this circuit extending from ground at RC471 by way of RA476, any one of the multiplied contacts numbered from one to 65 nine of the set 482, the switch wiper 484, and through the winding of R470 to battery. The relay R470 operates, when energized over the above-traced circuit, and opens, at RA471, a point in the impulsive circuit for the magnet 485, 70 thereby to prevent the switch 480 from thereafter responding to any further impulses dialed at the calling substation. Under the conditions assumed, the wiper 483 is standing in engagement with one of the contacts of the set 481 75 numbered from one to nine and, hence, no cir-

cuit is completed for energizing the switching relay R460. Thus, the loop circuit extending to the line switch 138 is held open. It will be apparent that, with R470 operated and the wipers of the switch 480 standing in any one of the 5 positions numbered from one to nine, further operation of the impulsive device provided at the substation E is of no effect, even though the relays R415, R428, R450 and R440 respond to these impulses. When the dialing operation is completed, 10 the link remains operated until the calling party hangs up to initiate the release of the link in the manner pointed out above or until the time controlled link release relay R580 is caused to operate. During the release of the link, the relay R470 is caused to restore when the wipers of the minor switch 480 are returned to normal. 15

Reverting calls

As pointed out in the introductory portion of 20 the specification, direct signalling is utilized on reverting calls between the substations associated with the respective rural lines, and another feature of the present invention pertains to the arrangement of the apparatus whereby none of the 25 regular automatic switching equipment provided in the automatic exchange is taken for use by a rural line having a reverting call initiated thereon and whereby a calling line is marked as busy for a fixed interval only, when occupied with a 30 reverting call. To initiate a call to the substation D, for example from the substation E, the calling party first listens in on the line to determine whether or not it is idle, in the manner pointed out above. If the line is found to be 35 idle, the receiver 615 is restored to its hook and the magneto generator 605 is actuated in accordance with the call signal corresponding to or identifying the substation D. The ringer or signal device at this substation, as well as the other 40 similar devices individually provided at the other substations associated with the line 600, responds to the ringing current projected over the line by the generator 605, and the resulting operation of these devices indicates that the substation D is 45 being called to the exclusion of all of the other substations associated with the line. Following 50 the ringing operation, the connection is completed when the calling and called parties remove their receivers from the respective associated hooks. In this connection, it is pointed out that the latch 624, provided at the calling substation, is moved to a position to permit closure of the contacts 625, whereby the above-traced metallic bridging path is connected across 55 the conductors C601 and C602 of the line 600.

When the magneto generator 605 is operated at the calling substation, the alternating current relay R405 is caused to operate in the manner pointed out above and, upon operating, completes, at RA407, the above-traced circuit over 60 which its lower winding is energized in series with the start relay R520. Thus, an idle one of the finder-repeater links is caused to operate to seize the line 600. Assuming that the link illustrated 65 is the link assigned to the use of the calling line, the operation of the link to search for and seize the line is identical with that described above. When the line is found, R400 operates to extend ground from RA414' to the control conductor 70 C603, thereby to mark the line 600 as busy in the bank contacts of the connector switches to which the line extends. Also, the relay R410 is caused to operate to switch the calling line through to the repeater portion of the link, in the manner 75

pointed out above. When this occurs, R415, R420, R430 and R560 operate, in the order named, and the last-mentioned relay completes, at RA561 and RC563, the above-traced holding circuit for R410. The relay R560 also marks the link as busy in the bank contacts of the allotter switch by impressing ground potential on the tenth contact of the set 505. Since, on a reverting call, no operation of the impulsive device provided at the calling substation is necessary, no further operations occur in the seized link following the operation of R560. Hence, it will be apparent that none of the regular switching equipment provided in the automatic exchange is assigned to the use of the calling line. The seized link remains in its partially operated condition until the connection is cleared out at both the calling and called substations or until the link release relay R580 is caused to operate to initiate the release of the operated link. If, for example, the duration of the conversation is such that the connection is cleared out before the operation of R580 occurs, by removal of the two metallic bridges from across the conductors 25 of the line 600 at the calling and called substations, respectively, the line relay R415 restores to initiate the release of the link in the exact manner pointed out with reference to the call extended by way of the link to the substation A.

50 If, on the other hand, the duration of the call is unusually long, the operated finder-repeater link is automatically released, the busy marking is removed from the control conductor C603 of the line, a marking identifying this line as idle 35 in the bank contacts of the connector switches to which it extends is substituted for the busy marking, and a signal is projected over the line to the conversing parties to indicate that the line is no longer guarded against seizure by one of the 40 connector switches. More particularly, when R560 operates following seizure of the link, it prepares, at RA564, a circuit for energizing the upper winding of R570. This circuit is subsequently completed when a ground pulse is impressed on the conductor C567 by the pulse generator 575. The relay R570, upon operating, completes, at RA571, a holding circuit for itself, which circuit extends from ground at RA465 by way of RA582, RA571 and the lower winding of 45 R570 to battery. At RA572, the relay R570, upon operating, prepares a circuit for energizing the link release relay R580. This latter relay is only energized when the second ground pulse is applied to C573. The pulse generator 575 is so 50 arranged that the time interval elapsing between the first and second ground pulses is sufficient to enable any conversation of ordinary length to be terminated. For example, this time interval may be of the order of five minutes. When 55 R580 operates in response to the application of ground to C573 by the generator 575, it completes, at RA583, a path for conducting a distinctive tone producing, alternating current by way of the secondary windings of the repeater 472. Specifically, 60 the path of this current extends from the ungrounded terminal of the alternating current source, not shown, by way of C584, the condenser 585, RA583, RC468, RA466, RA455, the repeater winding 479, the condenser 456', and the winding 478 to ground at the upper contact associated with RA463. The alternating nature of this current causes an induced voltage to be developed in the primary windings of the repeater 472, and this induced voltage results in the projection of 65

an alternating current through the receivers being used by the calling and called parties.

When R580 operates, it also opens, at RA582, a point in the common portion of the holding circuit for R570 and the circuit over which the lower winding of R560 is held energized. At RA581, it opens a point in the circuit including the upper winding of R560. When R570 restores, it opens a further point in its holding circuit and, at RA572, a point in the operating circuit for R580. The relay R560, upon restoring, opens, at RA561 and RC563, the holding circuit for R410, causing the latter relay to restore. The restoration of R410, in turn, causes the sequential restoration of R415, R420 and R430 in the order named and 10 in the manner pointed out above. When R410 restores, it also removes ground from the conductor C603 of the line 600 and opens the holding circuit for R400. Thus, the busy marking is removed from the control conductor C603, and 20 battery is extended through the winding of R400 to this conductor to identify the line as idle. When R430 restores, it opens, at RA435, an additional point in the circuit for energizing the upper winding of R560, thus preventing this latter relay from reoperating. In this connection, it is pointed out that the restoration of R430 occurs before the restoration of R580, so that R560 is prevented from reoperating. When R580 finally restores, it opens, at RA583, a point in the 30 path for conducting the signalling current through the secondary windings of the repeater 472. Following the restoration of R580, the link is completely released and is in readiness for further use. 35

It will be apparent that the equipment just described, namely, the two relays R570 and R580 and the pulse generator 575, functions to cause the release of the associated link in any case when a connection is not forwarded by way of the 40 trunk line 125 to the regular automatic switching equipment within a predetermined time interval after the link is taken for use. Thus, on a regular call to one of the single party lines, such, for example, as the line 101, if, for some reason, the 45 required ten impulses are not delivered to the switch 480 to cause this switch to operate and complete a circuit for energizing R460, the indicated apparatus will cause the release of the link providing the calling line is not released at the 50 calling substation within a predetermined time interval. When, however, a connection is extended by way of the trunk line 125 to the regular automatic switching equipment through the operation of R460, no holding circuit is thereafter 55 available for holding R570 operated and the link release apparatus is prevented from operating. Thus, when R460 operates, it opens, at RA465, a point in the above-traced holding circuit for R570. If the last-mentioned relay has been 60 caused to operate before R460 operates, it will restore to open, at RA572, the operating circuit for R580. If, on the other hand, R570 is not operated at the time R460 operates, it will only momentarily be energized when the first ground 65 pulse is applied to C567, and will immediately restore when the ground pulse is over. Under the last-described condition, when the second ground pulse is applied to C573, no completed circuit is available for energizing R580 and, 70 hence, the time controlled apparatus is rendered ineffective to cause the release of the link.

While there has been described what is at present considered to be the preferred embodiment of the invention, it will be understood that 75

various modifications may be made therein, and it is intended to cover in the appended claims all such modifications as fall within the true spirit and scope of the invention.

5. We claim:

1. In a telephone system, an exchange, a non-numerical automatic switch in said exchange, a subscriber's line extending to said exchange, said non-numerical switch being arranged to be used in setting up connections between said line and the other lines of the system, a numerical automatic switch in said exchange and arranged to have access to said line, a plurality of substations associated with said line, means comprising magnet generators individually provided at said stations for signalling between said stations on reverting calls, means for preventing said non-numerical switch from operating in response to the initiation of a reverting call on said line, thereby to prevent said non-numerical switch or any of the equipment accessible thereto from being rendered busy in the setting up of the reverting call connection, means for marking said line as busy when a reverting call is initiated on said line, thereby to prevent said line from being seized by said numerical switch, a plurality of additional lines extending to said exchange, and means responsive to the initiation of another and non-concurrent call at one of said substations intended for one of said additional lines for causing said non-numerical switch to be taken for use by said subscriber's line.

2. In a telephone system, an exchange, a non-numerical switch and a plurality of impulse responsive numerical switches located in said exchange, a repeater, a trunk line terminating at one of said numerical switches and at said non-numerical switch, said trunk line extending to said repeater, a subscriber's line extending to said repeater, a plurality of substations associated with said line, means for signalling between said stations on reverting calls, a normally incomplete loop circuit extending from said repeater to said non-numerical switch and arranged to cause the operation of said non-numerical switch when completed, said loop circuit including said trunk line, means responsive to the initiation of a reverting call on said line for marking said line as busy, thereby to prevent said line from being seized by said numerical switch, and means whereby said loop circuit is maintained incomplete when reverting calls are initiated on said line.

3. In a telephone system, an exchange, a plurality of lines extending to said exchange, automatic switching equipment including subscriber controlled automatic switches for setting up connections between said lines, a plurality of multi-party subscribers' lines extending to said exchange, said last-named lines being accessible to said switching equipment, a plurality of additional automatic switches controllable by impulses transmitted over said multi-party subscribers' lines, means controlled by said switches for rendering said equipment accessible to said multi-party subscribers' lines, and means including said switches for preventing any of said switching equipment from being seized in response to the initiation of reverting calls on any of said multi-party subscribers' lines.

4. In a telephone system, an exchange, a plurality of lines extending to said exchange, automatic switching equipment for setting up connections between said lines, a plurality of additional lines extending to said exchange, said last-

named lines being accessible to said switching equipment, a plurality of finder-repeater links for rendering said equipment accessible to said additional lines, and allotter means for assigning said finder-repeater links to successive calling ones of said additional lines in a definite order.

5. In a telephone system, an exchange, a plurality of lines extending to said exchange, automatic switching equipment for setting up connections between said lines, a plurality of multi-party subscribers' lines extending to said exchange, said last-named lines being accessible to said switching equipment, a plurality of finder-repeater links for rendering said equipment accessible to said subscribers' lines, allotter means for assigning said finder-repeater links to successive calling ones of said subscribers' lines in a definite order, said allotter means being arranged to assign said links to the use of said subscribers' lines when reverting calls are initiated on said subscribers' lines, and means included in each link for preventing any of said switching equipment from being seized when the link is assigned to a subscriber's line having a reverting call initiated thereon.

6. In a telephone system, an exchange, a plurality of lines extending to said exchange, a plurality of non-numerical automatic switches, a plurality of impulse responsive numerical switches, means including said switches for setting up connections between said lines, a plurality of additional lines extending to said exchange and accessible to certain of said numerical switches, and means responsive to a predetermined series of impulses transmitted thereto by way of a calling one of said additional lines for connecting the calling line through to one of said non-numerical switches.

7. In a telephone system, an exchange, a plurality of lines extending to said exchange, a plurality of non-numerical automatic switches, a plurality of impulse responsive numerical switches, means including said switches for setting up connections between said lines, a plurality of additional lines extending to said exchange and accessible to certain of said numerical switches, a plurality of finder-repeater links, allotter means for assigning said finder-repeater links to successive calling ones of said additional lines in a definite order, and means included in each link and responsive to a predetermined series of impulses transmitted thereto by way of an associated calling one of said additional lines for connecting the calling line through to one of said non-numerical switches.

8. In a telephone system, an exchange, a plurality of lines extending to said exchange, a plurality of non-numerical automatic switches, a plurality of impulse responsive numerical switches, means including said switches for setting up connections between said lines, a plurality of additional lines extending to said exchange and accessible to certain of said numerical switches, a plurality of finder-repeater links, allotter means for assigning said links to successive calling ones of said additional lines in a definite order, means including said links, said non-numerical switches and said numerical switches for setting up connections between said additional lines and said first-named plurality of lines on calls initiated on said additional lines, and means responsive to the initiation of calls on said additional lines for marking the calling lines as busy, thereby to prevent the

seizure of said calling lines by said numerical switches.

9. In a telephone system, an exchange, a plurality of lines extending to said exchange, a plurality of non-numerical switches, a plurality of impulse responsive numerical switches, means including said switches for setting up connections between said lines, a plurality of multi-party subscribers' lines extending to said exchange and accessible to certain of said numerical switches, a plurality of automatic switches for rendering said non-numerical switches accessible to said multi-party lines, means including said automatic switches, said non-numerical switches and said numerical switches for setting up connections between said multi-party subscribers' lines and said first-named plurality of lines on calls initiated on said multi-party subscribers' lines, and means responsive to the initiation of a reverting call on any one of said multi-party subscribers' lines for busying said one line to said numerical switches for a predetermined time interval only.

10. In a telephone system, an exchange, a plurality of lines extending to said exchange, a plurality of non-numerical switches, a plurality of impulse responsive numerical switches, means including said switches for setting up connections between said lines, a plurality of multi-party subscribers' lines extending to said exchange and accessible to certain of said numerical switches, a plurality of automatic switches for rendering said non-numerical switches accessible to said multi-party lines, means including said automatic switches, said non-numerical switches and said numerical switches for setting up connections between said multi-party subscribers' lines and said first-named plurality of lines on calls initiated on said multi-party subscribers' lines, means responsive to the initiation of a call on any one of said multi-party subscribers' lines for marking said one line as busy, thereby to prevent the seizure of said one line by said numerical switches, and means operative in the event said call on said one of said multi-party subscribers' lines is a reverting call for removing said busy marking and for marking said one line as idle.

11. In a telephone system, an exchange, a plurality of lines extending to said exchange, a plurality of non-numerical automatic switches, a plurality of impulse responsive numerical switches, means including said switches for setting up connections between said lines, a plurality of multi-party subscribers' lines extending to said exchange and accessible to certain of said numerical switches, means responsive to the initiation of a call on any one of said multi-party subscribers' lines for marking said one line as busy, thereby to prevent the seizure of said one line by said numerical switches, and means responsive to a series of impulses transmitted thereto by way of said one line for connecting said one line through to one of said non-numerical switches.

12. In a telephone system, an exchange, a plurality of lines extending to said exchange, a plurality of non-numerical automatic switches, a plurality of impulse responsive numerical switches, means including said switches for setting up connections between said lines, a plurality of additional lines extending to said exchange and accessible to certain of said numerical switches, a plurality of impulse responsive test links, allotter means for assigning said links

to successive calling ones of said additional lines in a definite order, means responsive to the initiation of a call on any one of said additional lines for marking said one line as busy, thereby to prevent the seizure of said one line by said numerical switches, and means included in an assigned link and responsive to a predetermined series of impulses transmitted thereto by way of said one line for connecting said one line through to one of said non-numerical switches. 10

13. In a telephone system, an exchange, a plurality of lines extending to said exchange, a plurality of non-numerical automatic switches, a plurality of impulse responsive numerical switches, means including said switches for setting up connections between said lines, a plurality of additional lines extending to said exchange and accessible to certain of said numerical switches, a plurality of impulse responsive test links, allotter means for assigning said links to successive calling ones of said additional lines in a definite order, means including said links for rendering said non-numerical switches accessible to said additional lines, and means individually associated with said additional lines 25 and individually operative in response to the seizure of the respective associated lines by said numerical switches for preventing any of said test links from being assigned to the use of the respective associated lines. 30

14. In a telephone system, an exchange, a plurality of lines extending to said exchange, a plurality of non-numerical automatic switches, a plurality of impulse responsive numerical switches, means including said switches for setting up connections between said lines, a plurality of additional lines extending to said exchange and accessible to certain of said numerical switches, a plurality of impulse responsive test links, allotter means for assigning said links to successive calling ones of said additional lines in a definite order, means associated with each of said additional lines and individually operative in response to the seizure of the associated lines by said numerical switches for preventing any of 40 said links from being assigned to the use of the associated lines, means included in each link and operative in response to the seizure thereof by a calling one of said additional lines for marking the associated line as busy, thereby to prevent 50 its seizure by one of said numerical switches, means included in each link and operative a predetermined time interval after the operation of said last-named means for substituting for said busy marking a marking identifying the calling 55 line as idle, means included in each link and responsive to one or more impulses transmitted by way of the calling line for preventing the operation of said last-named means, and means included in each link and responsive only to a predetermined series of impulses transmitted by way 60 of the calling line for connecting the calling line through to one of said non-numerical switches. 65

15. In a telephone system, an exchange, automatic switching equipment in said exchange, said equipment including a connector switch, a subscriber's line extending to said exchange and terminating at said connector switch, a plurality of substations associated with said line, means comprising magneto generators individually provided 70 at said substations for signalling between said substations on reverting calls, means associated with said line and operative in response to the operation of any one of said generators for marking said line as busy, thereby to prevent said 75

connector switch from seizing said line, and means operative a predetermined time interval after the operation of said last-named means and independently of the idle or busy condition of said line for removing said busy marking and for substituting a marking identifying said line as idle.

16. In a telephone system, an exchange, automatic switching equipment in said exchange, said equipment including a connector switch, a subscriber's line extending to said exchange and terminating at said connector switch, a plurality of substations associated with said line, means comprising alternating current generators individually provided at said substations for signalling between said substations on reverting calls, an alternating current relay associated with said line and operative in response to the operation of any one of said generators, means responsive to the operation of said relay for marking said line as busy, thereby to prevent said line from being seized by said connector switch, and means operative a predetermined time interval after the operation of said last-named means and independently of the idle or busy condition of said line for removing said busy marking and for substituting a marking identifying said line as idle.

17. In a telephone system, an exchange, automatic switching equipment in said exchange, said equipment including a connector switch, a subscriber's line extending to said exchange and terminating at said connector switch, a plurality of substations associated with said line, means comprising magneto generators individually provided at said substations for signalling between said substations on reverting calls, timing means, means associated with said line and operative in response to the operation of any one of said generators for marking said line as busy, thereby to prevent said connector switch from seizing said line, and means conditioned to respond to the operation of said timing means following the operation of said last-named means for removing said busy marking and for substituting a marking identifying said line as idle.

18. In a telephone system, an exchange, automatic switching equipment in said exchange, said equipment including a connector switch, a test link including a finder switch and a trunk extending to said equipment, a subscriber's line extending to said exchange and accessible to said connector switch and the finder switch of said link, a plurality of substations associated with said line, means comprising magneto generators individually provided at said substations for signalling between said substations on reverting calls, means associated with said line and operative in response to the operation of any one of said generators for causing said finder switch to search for and seize said subscriber's line, and means responsive to the seizure of said line for marking said line as busy, thereby to prevent said connector switch from seizing said line.

19. In a telephone system, an exchange, automatic switching equipment in said exchange, said equipment including a connector switch, a test link including a finder switch and a trunk extending to said equipment, a subscriber's line extending to said exchange and accessible to said connector switch and the finder switch of said link, a plurality of substations associated with said line, means comprising magneto generators individually provided at said substations for signalling between said substations on reverting

calls, means associated with said line and operative in response to the operation of any one of said generators for causing said finder switch to search for and seize said subscriber's line, means responsive to the seizure of said line for marking said line as busy, thereby to prevent said connector switch from seizing said line, and means operative a predetermined time interval after the operation of said last-named means for releasing said link, whereby said busy marking is removed and a marking identifying said line as idle is substituted for the busy marking.

20. In a telephone system, an exchange, automatic switching equipment in said exchange, said equipment including a connector switch, a test link including a finder switch and a trunk extending to said equipment, a subscriber's line extending to said exchange and accessible to said connector switch and the finder switch of said link, a plurality of substations associated with said line, means comprising magneto generators individually provided at said substations for signalling between said substations on reverting calls, an alternating current relay operative in response to the operation of any one of said generators, means responsive to the operation of said relay for causing said finder switch to search for and seize said subscriber's line, means responsive to the seizure of said line for marking said line as busy, thereby to prevent said connector switch from seizing said line, and means operative a predetermined time interval after the operation of said last-named means for releasing said link irrespective of the idle or busy condition of said line, whereby said busy marking is removed and a marking identifying said line as idle is substituted for said busy marking.

21. In a telephone system, an exchange, automatic switching equipment in said exchange, said equipment including a connector switch, a test link including a finder switch and a trunk extending to said equipment, a subscriber's line extending to said exchange and accessible to said connector switch and the finder switch of said link, a plurality of substations associated with said line, means comprising magneto generators individually provided at said substations for signalling between said substations on reverting calls, impulsive devices individually provided at certain of said substations, means associated with said line and operative in response to the operation of any one of said generators for causing said finder switch to search for and seize said line, means responsive to the seizure of said line by said finder switch for marking said line as busy, thereby to prevent said line from being seized by said connector switch, and means responsive to a predetermined operation of the impulsive device at said one station for effectively connecting said line by way of said finder switch and said trunk to said automatic switching equipment and for conditioning said equipment to respond to further operation of the impulsive device at said one station.

22. In a telephone system, an exchange, automatic switching equipment in said exchange, said equipment including a connector switch, a test link including a finder switch and a trunk extending to said equipment, a subscriber's line extending to said exchange and accessible to said connector switch and the finder switch of said link, a plurality of substations associated with said line, means comprising magneto generators individually provided at said substations for signalling between said substations on re-

verting calls, impulsing devices individually provided at certain of said substations, means associated with said line and operative in response to the operation of any one of said generators for causing said finder switch to search for and seize said line, means responsive to the seizure of said line by said connector switch for preventing said last-named means from operating, means responsive to the seizure of said line by said finder switch for marking said line as busy, thereby to prevent said line from being seized by said connector switch, and means responsive to a predetermined operation of the impulsing device at said one station for effectively connecting said line by way of said finder switch, and said trunk to said automatic switching equipment and for conditioning said equipment to respond to further operation of the impulsing device at said one station.

23. In a telephone system, an exchange, automatic switching equipment in said exchange, said equipment including a connector switch, a test link including a finder switch and a trunk extending to said equipment, a subscriber's line extending to said exchange and accessible to said connector switch and the finder switch of said link, a plurality of substations associated with said line, means comprising magneto generators individually provided at said substations for signalling between said substations on reverting calls, means associated with said line and operative in response to the operation of any one of said generators for causing said finder switch to search for and seize said line, and means responsive to the seizure of said line by said connector switch for preventing said last-named means from operating.

24. In a telephone system, an exchange, automatic switching equipment in said exchange, said equipment including a connector switch, a subscriber's line extending to said exchange and accessible to said connector switch, a plurality of substations associated with said line, means comprising magneto generators individually provided at said substations for signalling between said substations on reverting calls, an alternating current relay including a winding normally connected across the conductors of said line, whereby said relay is normally operative in response to the operation of any one of said generators, means including means responsive to the operation of said relay for rendering said automatic switching equipment accessible to said line, and means responsive to the seizure of said line by said connector switch for disconnecting the winding of said relay from across the conductors of said line.

25. In a telephone system, an exchange, automatic switching equipment in said exchange, said equipment including a connector switch, a test link including a finder switch and a trunk extending to said equipment, a subscriber's line extending to said exchange and accessible to said connector switch and the finder switch of said link, a plurality of substations associated with said line, means comprising magneto generators individually provided at said substations for signalling between said substations on reverting calls, an alternating current relay including a winding normally connected across the conductors of said line, whereby said relay is operative in response to the operation of any one of said generators, means responsive to the operation of said relay for causing said finder switch to search for and seize said line, and means responsive to the seizure of said line by said connector

switch for disconnecting the winding of said relay from across the conductors of said line.

26. In a telephone system, an exchange, automatic switching equipment in said exchange, said equipment including a connector switch, a test link including a finder switch and a trunk extending to said equipment, a subscriber's line extending to said exchange and accessible to said connector switch and the finder switch of said link, a plurality of substations associated with said line, means comprising magneto generators individually provided at said substations for signalling between said substations on reverting calls, impulsing devices individually provided at certain of said substations, means associated with said line and operative in response to the operation of the generator at one of said substations for causing said finder switch to search for and seize said line, means operative a predetermined time interval after the operation of said last-named means for releasing said link, and means responsive to the operation of the impulsing device at said one substation for preventing the operation of said last-named means.

27. In a telephone system, an exchange, automatic switching equipment in said exchange, said equipment including a connector switch, a test link including a finder switch and a trunk extending to said equipment, a subscriber's line extending to said exchange and accessible to said connector switch and the finder switch of said link, a plurality of substations associated with said line, means comprising magneto generators individually provided at said substations for signalling between said substations on reverting calls, impulsing devices individually provided at certain of said substations, means associated with said line and operative in response to the operation of the generator at one of said substations for causing said finder switch to search for and seize said line, means operative a predetermined time interval after the operation of said last-named means for releasing said link, means responsive to the operation of the impulsing device at said one substation for preventing the operation of said last-named means, and means responsive only to a predetermined operation of the impulsing device at said one substation for effectively connecting said line by way of said finder switch and said trunk to said switching equipment and for conditioning said equipment to respond to further operation of the impulsing device at said one substation.

28. In a telephone system, an exchange, automatic switching equipment in said exchange, said equipment including a connector switch, a test link including a finder switch and a trunk extending to said equipment, a subscriber's line extending to said exchange and accessible to said connector switch and the finder switch of said link, a plurality of substations associated with said line, means comprising magneto generators individually provided at said substations for signalling between said substations on reverting calls, impulsing devices individually provided at certain of said substations, means associated with said line and operative in response to the operation of the generator at one of said substations for causing said finder portion of said link to search for and seize said line, means responsive to the seizure of said line by said finder switch for making said line as busy, thereby to prevent said line from being seized by said connector switch, means operative a predetermined time interval after the seizure of said line for

releasing said link thereby to substitute for said busy marking a marking identifying said line as idle, and means responsive to the operation of the impulsive device at said one substation for preventing the operation of said last-named means.

29. In a telephone system, an exchange, automatic switching equipment in said exchange, said equipment including a connector switch, a test link including a finder switch and a trunk extending to said equipment, a subscriber's line extending to said exchange and accessible to said connector switch and the finder switch of said link, a plurality of substations associated with said line, means comprising magneto generators individually provided at said substations for signalling between said substations on reverting calls, impulsive devices individually provided at certain of said substations, means associated with said line and operative in response to the operation 10 of the generator at one of said substations for causing said finder switch to search for and seize said line, means responsive to the seizure of said line by said finder switch for marking said line as busy, thereby to prevent said line 15 from being seized by said connector switch, means operative a predetermined time interval after the seizure of said line for releasing said link, thereby to substitute a marking identifying said line as idle for said busy marking, means 20 responsive to the operation of the impulsive device at said one substation for preventing the operation of said last-named means, and means responsive only to a predetermined operation of the impulsive device at said one substation for 25 effectively connecting said line by way of said finder switch and said trunk to said switching equipment and for conditioning said equipment to respond to further operation of the impulsive device at said one substation.

40 30. In a telephone system, an exchange, automatic switching equipment in said exchange, said equipment including a connector switch, a test link including a finder switch and a trunk extending to said equipment, a subscriber's line extending to said exchange and accessible to said connector switch and the finder switch of said link, a plurality of substations associated with said line, means comprising magneto generators individually provided at said substations for signalling between said substations on reverting calls, impulsing devices individually provided at certain of said substations, means associated with said line and operative in response to the operation of the generator at one of said substations for causing said finder switch to search for and seize said line, means responsive to the seizure of said line by said connector switch for preventing said last-named means from operating, means operative to release said link a predetermined time interval after the operation of said last-named means, and means responsive to the operation of the impulsing device at said one substation for preventing the operation of said last-named means.

65 31. In a telephone system, an exchange, automatic switching equipment in said exchange, said equipment including a connector switch, a test link including a finder switch and a trunk extending to said equipment, a subscriber's line extending to said exchange and accessible to said connector switch and the finder switch of said link, a plurality of substations associated with said line, means comprising magneto generators individually provided at said substations for signalling between said substations on reverting

70

75

calls, impulsive devices individually provided at certain of said substations, means associated with said line and operative in response to the operation of the generator at one of said substations for causing said finder switch to search for and seize said line, means responsive to the seizure of said line by said connector switch for preventing said last-named means from operating, means operative to release said link a predetermined time interval after the operation of said finder switch to seize said line, means responsive to the operation of the impulsive device at said one substation for preventing the operation of said last-named means, and means responsive only to a predetermined operation of the impulsive device at said one substation for effectively connecting said line by way of said finder switch and said trunk to said switching equipment and for conditioning said equipment to respond to further operation of the impulsive device at said one substation. 5 10 15 20

32. In a telephone system, an exchange, automatic switching equipment in said exchange, said equipment including a connector switch, a test link including a finder switch and a trunk extending to said equipment, a subscriber's line extending to said exchange and accessible to said connector switch and the finder switch of said link, a plurality of substations associated with said line, means comprising magneto generators individually provided at said substations for signalling between said substations on reverting calls, impulsing devices individually provided at certain of said substations, means associated with said line and operative in response to the operation of the generator at one of said substations for causing said finder switch to search for and seize said line, means responsive to the seizure of said line by said connector switch for preventing said last-named means from operating, means responsive to the seizure of said line by said finder switch for marking said line as busy, thereby to prevent said line from being seized by said connector switch, means operative a predetermined time interval after the seizure of said line by said finder switch for releasing said link, thereby to substitute for said busy marking a marking identifying said line as idle, and means responsive to the operation of the impulsing device at said one substation for preventing the operation of said last-named means.

33. In a telephone system, an exchange, automatic switching equipment in said exchange, said equipment including a connector switch, a test link including a finder switch and a trunk extending to said equipment, a subscriber's line extending to said exchange and accessible to said connector switch and the finder switch of said link, a plurality of substations associated with said line, means comprising magneto generators individually provided at said substations for signalling between said substations on reverting calls, impulsing devices individually provided at certain of said substations, means associated with said line and operative in response to the operation of the generator at one of said stations for causing said finder switch to search for and seize said line, means responsive to the seizure of said line by said connector switch for preventing said last-named means from operating, means responsive to the seizure of said line by said finder switch for marking said line as busy, thereby to prevent said line from being seized by said connector switch, means operative a predetermined time interval after the seizure of said line by said 55 60 65 70 75

6 finder switch for releasing said link thereby to substitute for said busy marking a marking identifying said line as idle, means responsive to the operation of the impulsive device at said one substation for preventing the operation of said last-named means, and means responsive only to a predetermined operation of the impulsive device at said one substation for effectively connecting said line by way of said finder switch and said 10 trunk to said switching equipment and for conditioning said equipment to respond to further operation of the impulsive device at said one station.

34. In a telephone system, a line, a repeater 15 comprising a pair of link lines adapted to be connected together for the purpose of extending a connection routed by way of said first-named line, means operative to connect said link lines together, automatic switching means operative in 20 response to impulses transmitted by way of said first-named line, and means comprising said switching means for causing the operation of said first-named means only when a predetermined series of impulses is transmitted by way of said 25 first-named line to said switching means.

35. In a telephone system, a line, a repeater comprising a pair of link lines adapted to be connected together for the purpose of extending a connection routed by way of said first-named 30 line, means operative to connect said link lines together, automatic switching means operative in response to impulses transmitted by way of said first-named line, said switching means being operative to a predetermined position to cause the 35 operation of said first-named means only when a predetermined series of impulses are transmitted thereto by way of said first-named line, and means responsive to the operation of said switching means to any other active position for preventing said switching means from responding to 40 further impulses transmitted by way of said first-named line.

36. In a telephone system, a line, a repeater including a pair of link lines adapted to be connected together for the purpose of extending a connection routed by way of said first-named line, a relay operative to connect said link lines together, a rotary switch including bank contacts, wipers associated with said contacts and a magnet for driving said wipers over said contacts, 45 means responsive to impulses transmitted by way of said first-named line for repeatedly energizing said magnet to drive said wipers over said contacts, and an operating circuit for said relay, said 50 operating circuit including one of said contacts and one of said wipers and being completed only in response to the operation of said switch to move said one wiper into engagement with said one contact.

37. In a telephone system, a line, a repeater 55 including a pair of link lines adapted to be connected together for the purposes of extending a connection routed by way of said first-named line, a relay operative to connect said link lines together, a rotary switch including two sets of bank contacts, wipers respectively associated with said contact sets and a magnet for driving said wipers over the contacts of their respective associated sets, an operating circuit for said magnet, means responsive to impulses transmitted by 60 way of said first-named line for repeatedly energizing said magnet to drive said wipers over said contacts, an operating circuit for said relay, said last-named circuit including one contact of one of said contact sets and the associated wiper and 65

being completed only in response to the operation of said switch resulting from the transmission of a predetermined series of impulses by way of said first-named line, a relay operative to interrupt the operating circuit for said magnet, and an operating circuit for said last-named relay, said last-named circuit including one contact of the other of said contact sets and being completed in response to the operation of said switch resulting from the transmission of a series of impulses by way of said first-named line differing from said predetermined series of impulses. 70

38. In a telephone system, a subscriber's line including at least one conductor, a source of ringing current, a ringing current conductor, a control conductor, a cyclically operating switch for applying the voltage of said source to said ringing current conductor during each cycle of its operation, said switch being operative to apply a predetermined potential to said control conductor at the beginning of each cycle of its operation, means responsive to one application of said predetermined potential to said control conductor for connecting said ringing conductor to one of the conductors of said line, whereby ringing current is projected over said line, and means responsive to a predetermined subsequent application of said predetermined potential to said control conductor for disconnecting said ringing current conductor from said one line conductor. 20 25 30

39. In a telephone system, a subscriber's line including at least one conductor, a source of ringing current, a ringing current conductor, a control conductor, a cyclically operating switch for applying the voltage of said source to said ringing current conductor for coded intervals during each cycle of its operation, said switch being operative to apply a predetermined potential to said control conductor at the beginning of each cycle of its operation, and a plurality of relays connected and arranged sequentially to operate in response to successive applications of said predetermined potential to said control conductor, the first of said relays to operate being operative to connect said ringing current conductor to one of the conductors of said line, thereby to project ringing current over said line, and the last of said relays to operate being operative to disconnect said ringing current conductor from said one line conductor. 40 45 50 55

40. In a telephone system, a subscriber's line, an automatic switch operative to select said line, a trunk line incoming to said switch, means automatically operative to impress coded ringing voltage on said line following the operation of said switch to select said line, the code of said ringing voltage being cyclically repeated, and means automatically operative to connect said trunk line to said subscriber's line following the application of ringing voltage to said subscriber's line for a predetermined number of code cycles. 60 65

41. In a telephone system, a subscriber's line including at least one conductor, an automatic switch operative to select said line, a trunk line incoming to said switch, a source of ringing current, a ringing current conductor, a control conductor, a cyclically operating switch for applying the voltage of said source to said ringing current conductor for coded intervals during each cycle of its operation, said cyclically operating switch being operative to apply a predetermined potential to said control conductor at the beginning of each cycle of its operation, means responsive to one application of said predetermined potential to said control conductor for connecting said 70 75 80 85 90 95

- ringing current conductor to one of the conductors of said line, whereby ringing current is projected over said line, and means responsive to a predetermined subsequent application of said predetermined potential to said control conductor for disconnecting said ringing current conductor from said line conductor and for connecting said trunk line to said subscriber's line.
42. In a telephone system, a subscriber's line including at least one conductor, an automatic switch operative to select said line, a trunk line incoming to said switch, a source of ringing current, a ringing current conductor, a control conductor, a cyclically operating switch for applying the voltage of said source to said ringing current conductor for coded intervals during each cycle of its operation, said cyclically operating switch being operative to apply a predetermined potential to said control conductor at the beginning of each cycle of its operation, and a plurality of relays connected and arranged sequentially to operate in response to successive applications of said predetermined potential to said control conductor, the first of said relays to operate being operative to connect said ringing current conductor to one of the conductors of said line, thereby to project ringing current over said line, and the last of said relays to operate being operative to disconnect said ringing current conductor from said one line conductor and to connect said trunk line to said subscriber's line.
43. In a telephone system, a subscriber's line of the party line type, a final selector switch automatically operative to either of two positions to select said line, a pair of ringing current conductors each adapted to have applied thereto ringing voltage different in character from that applied to the other similar conductor, and means for connecting one of said ringing current conductors to project ringing current over said line when said switch is operated to one of said two positions and for connecting the other of said ringing current conductors to project ringing current over said line when said switch is operated to the other of said two positions.
44. In a telephone system, a subscriber's line of the party line type, a final selector switch automatically operative to either of two positions to select said line, a plurality of ringing current conductors arranged in two groups, each of said conductors being adapted to have applied thereto ringing voltage different in character from that applied to each of the other similar conductors, an impulse responsive switch operative to select a ringing current conductor from each of said two groups following the operation of said selector switch to select said line, and means for connecting one of the two selected ringing current conductors to project ringing current over said line when said selector switch is operated to one of said two positions and for connecting the other of said two selected ringing current conductors to project ringing current over said line when said selector switch is operated to the other of said two positions.
45. In a telephone system, a line, an impulsive device for transmitting impulses over said line, an impulse responsive device associated with said line and adapted to be connected to respond to impulses transmitted over said line, automatic switching equipment adapted to be arranged to respond to the operation of said impulse responsive device, and means for testing the sensitivity of said impulse responsive device to impulses transmitted over said line before arranging said

automatic switching equipment to respond to operation of said impulse responsive device.

46. In a telephone system, a subscriber's line, a substation associated with said line and including an impulsive device, a relay associated with said line and adapted to be connected to respond to impulses transmitted over said line through the operation of said impulsive device, automatic switching equipment adapted to be arranged to respond to the operation of said relay, and means for reducing the sensitivity of said relay to impulses transmitted over said line during one operation of said impulsive device and before arranging said automatic switching apparatus to respond to operation of said relay. 15

47. In a telephone system, a line, an impulsive device for transmitting impulses over said line, an impulse responsive device associated with said line and adapted to be connected to respond to impulses transmitted over said line, automatic switching equipment, means including said impulse responsive device responsive only to a predetermined series of impulses transmitted over said line for conditioning said switching equipment to respond to the operation of said impulse responsive device, and means for reducing the sensitivity of said relay to the impulses of said predetermined series only. 20

48. In a telephone system, a line, an impulsive device for transmitting impulses over said line, a relay associated with said line and adapted to be connected to respond to impulses transmitted over said line through the operation of said impulsive device, automatic switching equipment, means including said relay and responsive only to a predetermined series of impulses transmitted over said line for conditioning said switching equipment to respond to the operation of said relay, an artificial leak impedance normally connected and arranged to reduce the sensitivity of said relay to impulses transmitted over said line, 40 and means for rendering said leak impedance ineffective at the end of said series of impulses. 35

49. In a telephone system, a line, an impulsive device for transmitting impulses over said line, an impulse responsive device associated with said line and adapted to be connected to respond to impulses transmitted over said line, automatic switching equipment, control apparatus including said impulse responsive device and responsive only to a predetermined series of impulses transmitted over said line for conditioning said switching equipment to respond to the operation of said impulse responsive device, and means including said control apparatus for testing the responsiveness of said impulse responsive device to impulses transmitted over said line before said switching equipment is conditioned to respond to the operation of said impulse responsive device. 45 50

50. In a telephone system, a line, an impulsive device for transmitting impulses over said line, an impulse responsive device associated with said line and adapted to be connected to respond to impulses transmitted over said line, automatic switching equipment, control apparatus including said impulse responsive device and responsive only to a predetermined series of impulses transmitted over said line for conditioning said switching equipment to respond to the operation of said impulse responsive device, means including said control apparatus for testing the responsiveness of said impulse responsive device to impulses transmitted over said line before said switching equipment is conditioned to respond to the operation of said impulse responsive device, and means for preventing said switching equipment 75 70 75

ment from responding to the operation of said impulse responsive device in the event said impulse responsive device is not faithfully responsive to the impulses of said series of impulses.

- 5 51. In a telephone system, a line, an impulsive device for transmitting impulses over said line, an impulse responsive device associated with said line and adapted to be connected to respond to impulses transmitted over said line, automatic switching equipment, control apparatus including said impulse responsive device and responsive only to a predetermined series of impulses transmitted over said line for conditioning said switching equipment to respond to the operation of said impulse responsive device, means including said control apparatus for testing the responsiveness of said impulse responsive device to impulses transmitted over said line before said switching equipment is conditioned to respond to the operation of said impulse responsive device, and means for enhancing the responsiveness of said impulse responsive device to impulses transmitted over said line following the transmission of said predetermined series of impulses.
- 25 52. In a telephone system, a line, an impulsive device for transmitting impulses over said line, an impulse responsive device associated with said line and adapted to be connected to respond to impulses transmitted over said line, automatic switching equipment, control apparatus including said impulse responsive device and responsive only to a predetermined series of impulses transmitted over said line for conditioning said switching equipment to respond to the operation of said impulse responsive device, means including said control apparatus for testing the responsiveness of said impulse responsive device to impulses transmitted over said line before said switching equipment is conditioned to respond to the operation of said impulse responsive device, means for preventing said switching equipment from responding to the operation of said impulse responsive device in the event said impulse responsive device is not faithfully responsive to the impulses of said predetermined series of impulses.
- 35 40 45 50 55 60 65 70 75
53. In a telephone system, an exchange, automatic switching equipment in said exchange, said equipment including a connector switch, a subscriber's line extending to said exchange and terminating at said connector switch, a plurality of substations associated with said line, means comprising magneto generators individually provided at said substations for signalling between said substations on reverting calls, means associated with said line and operative in response to the operation of any one of said generators for marking said line as busy, thereby to prevent said connector switch from seizing said line, means operative a predetermined time interval after the operation of said last-named means and independently of the idle or busy condition of said line for removing said busy marking and for substituting a marking identifying said line as idle, and means operative at the time said busy marking is removed for signalling over said line that the line is no longer guarded against seizure by said connector switch.

54. In a telephone system, an exchange, automatic switching equipment in said exchange, said

equipment including a connector switch, a subscriber's line extending to said exchange and terminating at said connector switch, a plurality of substations associated with said line, means comprising magneto generators individually provided at said substations for signalling between said substations on reverting calls, means associated with said line and operative in response to the operation of any one of said generators for marking said line as busy, thereby to prevent said connector switch from seizing said line, means operative a predetermined time interval after the operation of said last-named means and independently of the idle or busy condition of said line for removing said busy marking and for substituting a marking identifying said line as idle, and means operative at the time said busy marking is removed for momentarily applying to said subscriber's line a tone current, whereby a signal is transmitted over said line to indicate that the line is no longer guarded against seizure by said connector switch.

55. In a telephone system, an exchange, a line extending to said exchange, a numerical switch arranged to serve said line, means for testing the impulse transmitting conditions of said line, and means controlled by said last-named means for preventing said numerical switch from serving said line until said first named means has operated to determine that the impulsive conditions of said line are satisfactory.

56. In a telephone system, an exchange, a line extending to said exchange, a telephone substation on said line and including an impulsive device, a numerical line selecting switch adapted to be connected to respond to impulses transmitted from said device, means for testing the ability of said lines to carry impulses from said device to said switch, and means controlled by said last-named means for preventing said switch from being connected to respond to impulses transmitted from said device until said first named means has operated to determine that the impulsive conditions of said line are satisfactory.

57. In a telephone system, an exchange, a plurality of lines extending to said exchange, said lines being divided into groups of different classes, a plurality of numerical switches arranged to serve all of said lines, means for testing the impulse transmitting conditions of the lines in at least one class, and means for preventing any of said numerical switches from serving a calling one of the lines in said one class until said first-named means has operated to indicate that the impulsive conditions of said one line are satisfactory.

58. In a signalling system, a line, means for transmitting impulses over said line, an automatic switch adapted to respond to impulses transmitted over said line, means for testing the impulse transmitting conditions of said line, and means controlled by said second named means for preventing said automatic switch from responding to impulses transmitted over said line until said second named means has operated to determine that the impulse transmitting conditions of said line are satisfactory.

59. In an automatic telephone system, an exchange, a plurality of lines extending to said exchange, automatic switching equipment for setting up connections between said lines, at least one of said lines being of the multi-party type, an additional impulse responsive automatic switch controllable over said multi-party line, and means controlled by said switch for render-

ing said equipment accessible to said multi-party line.

60. In an automatic telephone system, an exchange, a plurality of lines extending to said exchange, automatic switching equipment for setting up connections between said lines, one of said lines being of the multi-party type, means for signaling between the substations of said multi-party line on reverting calls, and means 10 for preventing any of said automatic switching equipment from being seized or from operating at any time during the setting up or duration of a reverting call connection, and for busying said multi-party line to said equipment when a reverting call is initiated on said multi-party line.

61. In an automatic telephone system, an exchange, a plurality of lines extending to said exchange, automatic switching equipment for setting up connections between said lines, one of 20 said lines being of the multi-party type, means comprising magneto generators individually provided at the substations of said multi-party line for signaling between said substations on reverting calls, means responsive to operation of any

one of said generators for busying said multi-party line to said equipment without seizing or causing the operation of any of said equipment, an additional impulse responsive automatic switch controllable over said multi-party line, and means controlled by said switch for rendering said equipment accessible to said multi-party line.

62. In a telephone system, a subscriber's line, an automatic switch selectively controllable over another line of the system to select said line, said automatic switch including means controllable over said other line for impressing coded ringing voltage on said subscriber's line, the code of said ringing voltage being cyclically repeated, means 15 for automatically removing said ringing voltage from said subscriber's line after said voltage has been applied to said subscriber's line for a pre-determined number of code cycles, and means for establishing a talking circuit through said switch 20 and extending between said lines.

HARRY PAUL MAHONEY.
CLARENCE ERNEST LOMAX.

CERTIFICATE OF CORRECTION.

Patent No. 2,218,850.

October 22, 1940.

HARRY PAUL MAHONEY, ET AL.

It is hereby certified that error appears in the printed specification of the above numbered patent requiring correction as follows: Page 18, first column, line 67, claim 3, before the word "switches" insert --additional--; page 21, second column, line 72, claim 28, for "making" read --marking--; page 24, first column, line 19-20, claim 42, for "beginning" read --beginning--; page 25, second column, line 36, claim 56, for "impluses" read --impulses--; and that the said Letters Patent should be read with this correction therein that the same may conform to the record of the case in the Patent Office.

Signed and sealed this 3rd day of December, A. D. 1940.

(Seal)

Henry Van Arsdale,
Acting Commissioner of Patents.
